UNITED STATES PATENT OFFICE.

ALBEN E. LUNDELL AND EDGAR H. CLARK, OF NEW YORK, N. Y., ASSIGNEES TO
WESTERN ELECTRIC COMPANY, INCORPORATED, OF NEW YORK, N. Y., A
CORPORATION OF NEW YORK.

TELEPHONE-EXCHANGE SYSTEM.

1,342,823.

Specification of Letters Patent.

Patented June 8, 1920.

Application filed November 2, 1917. Serial No. 199,886.

To all whom it may concern:

Be it known that we, ALBEN E. LUNDELL and EDGAR H. CLARK, citizens of the United States, residing at New York, in the county of Bronx and State of New York, and at New York, in the county of New York and State of New York, respectively, have invented certain new and useful Improvements in Telephone-Exchange Systems, of which the following is a full, clear, concise, and exact description.

This invention relates to telephone exchange systems of the semi-automatic type, and more particularly to systems in which tandem trunking is required.

It is the object of this invention to provide a system in which subscribers' calls may be extended through a plurality of offices in tandem and to accomplish this end in a rapid and efficient manner.

In accordance with this object a switching center is provided, there being provided at this point an operator corresponding to a B operator, who will receive calls from outlying offices and who will then operate automatic switching mechanisms under the control of a key set to extend the calling line to a desired outlying office. From this outlying office the call may be extended by means of mechanical switches, or an indicator may be operated at this point to inform the operator at the "tandem point" of the number of the desired line. If the call is to be again trunked from this point through another distant office in tandem, the indicator will also inform the tandem point operator as to the office to which the call is to be trunked.

In the present disclosure it has been assumed that all calls will be extended to a tandem point operator who will trunk to an outlying office, it being obvious that if the call is for a number located at her own office she could readily complete the connection, and that in this case the indication of the last office would be omitted.

No disclosure has been made of the method by which calls may be completed at an outlying office provided with automatic switches for completing this type of connection, since this form of connection is well understood in the art.

A feature of the invention is the method of providing metallic supervision for the

various operators concerned in setting up the connection.

A further feature of the invention resides in an improved method for performing the operations necessary in handling the overflow condition, that is, the condition which arises when all the trunks of a selected group are busy.

Another feature of the invention resides in the provision and method of controlling two allotters which control the assignment of senders to the operator controlling the switching center.

A still further feature of the invention is provided by a novel test which is made by the sender to determine whether or not the operator at the tandem point has removed her plug from the jack, the object of this test being to delay the operation of the impulse sending device which controls the call indicating mechanism at such office until such operator is ready to receive a call.

An added feature of the invention is the provision of means to delay operation of the sender, when connection is being established to an interdistrict office selector, until such selector has arrived at its normal position and is ready for reoperation.

A further feature of the invention is an arrangement by which the stepping relay, that is, the relay which controls the successive operations of the counting relays in the sender, is used only on calls to a distant office; that is, if the office selector is local, the counting relays will be directly controlled from the commutator of the switch being operated; but if the call is extended through an interdistrict office, the stepping relay is utilized to insure greater accuracy.

Other features will appear from the following description and appended claims.

It is thought that the invention will best be understood from the following detailed description, reference being had to the accompanying drawings.

In the drawings, Figures 1 to 13 inclusive indicate diagrammatically a telephone exchange system embodying the principles of the present invention. Fig. 14 is a plan showing with what relation to one another the various sheets of drawings should be placed, it being understood, however, that Figs. 3 and 4 are interchangeable, dependent upon whether the call is to be ex-

tended through a local office selector or an interdistrict office selector.

Fig. 1 shows a calling subscriber's substation and a cord circuit at an A operator's position, as well as the outgoing end of a trunk to the cordless operator's position at the switching center; Fig. 2 shows the circuits of a district selector, all the sequence switch contacts shown in this figure being under the control of the sequence switch shown at the bottom of the figure, with the exception of the contacts within the dotted lines, which are utilized for overflow signaling under the control of the sequence switch shown in such dotted rectangle; Fig. 3 shows the circuits of a local office selector; Fig. 4 shows the circuits of an interdistrict office selector; Fig. 5 shows the circuits of an incoming trunk at a tandem point, together with the cord circuit of a manual operator at an outlying office and the substation apparatus of a called subscriber; Fig. 6 shows the circuits of a cord finder, while in the dotted rectangles are shown the circuits for controlling two allotters, there being a sequence switch associated with each allotter for controlling the contacts associated with it within the dotted lines; Figs. 7, 8 and 9 indicate sender circuits for registering a desired number and for transmitting suitable impulses for controlling the extension of the call; Figs. 10, 11, 12 and 13 show the circuits of the relay call indicator which controls the indication of the designation of the desired outlying office and of the desired line number.

The subscriber at substation 10 desiring to initiate a call removes his receiver from the hook, causing a line signal to be displayed before the A operator, one of whose cords is indicated at 0. The operator on observing this signal, inserts the plug 11 into answering jack 12 associated with the line signal of the calling subscriber and inquires the number of the wanted line. The operator at 0 by means of an order wire not shown, but which may be of any well-known type, converses with the operator at the switching center, whom we shall hereafter designate as the "cordless" operator, and upon being advised to use the trunk outgoing from jack 13, inserts plug 14 into jack 13 and extends the calling line to the operator's position shown in Fig. 2. When plug 14 is inserted into jack 13 a circuit is completed from grounded battery, lamp 15, resistance 17, sleeve conductors of plug 14 and jack 13, winding of relay 18, to ground. Relay 18 is energized in this circuit and lamp 15 is lighted.

A circuit is now completed from ground, lower right-hand contact of sequence switch spring 19, conductor 20, lower winding of relay 21, lower right-hand winding of repeating coil 22, armature and front contact

of relay 18, winding of polarized relay 23, upper right-hand winding of repeating coil 22, trunk conductor 24, upper winding of relay 21, upper right-hand contact of sequence switch spring 25, to grounded battery. Flow of current in this circuit is in such a direction as not to energize polarized relay 23, but relay 21 is energized, completing a circuit from ground, armature and front contact of relay 21, upper right-hand and lower left-hand contacts of sequence switch spring 26, lamp 27, to grounded battery. Lamp 27 is lighted to inform the cordless operator that the A operator has plugged in on the assigned trunk. The cordless operator then momentarily depresses non-locking assignment key 28, whereupon a circuit is completed from grounded battery, power magnet of sequence switch 29, upper contact of sequence switch spring 30, closed lower contacts of key 28, to ground. Sequence switch 29 moves from position 1 to position 2 under the control of its normal contact 31.

It is to be observed at this point that if at the time the assignment key is depressed the sequence switch associated with any other district selector is standing in position 2, it will be immediately moved out of position 2 and restored to its normal position, when the sequence switch shown in Fig. 2 arrives in position 2. This would occur as follows. The relay corresponding to relay 32 associated with such other selector would be energized over a circuit extending from grounded battery, left-hand winding of said relay corresponding to relay 32, right-hand contacts of a sequence switch spring corresponding to sequence switch spring 33, through the closed contacts of the assignment key associated with such selector and corresponding to key 28, through the multiplied movable upper contact at the depressed assignment key 28 to ground. This relay when energized completes a locking circuit for itself from grounded battery, its right-hand winding, upper right-hand contact of a sequence switch spring corresponding to sequence switch spring 34, right-hand armature and front contact of relay 32, left-hand contacts of a sequence switch spring corresponding to sequence switch spring 35, to ground. This relay would then complete a circuit from grounded battery, power magnet of its associated sequence switch, lower right-hand contact of a sequence switch spring corresponding to sequence switch spring 30, left-hand armature and front contact of relay 32, lower right and upper left contacts of a sequence switch spring corresponding to sequence switch spring 26, to ground, for moving its associated sequence switch through positions 2 and 3. The relay corresponding to relay 32 is deenergized when the associated sequence switch leaves

- position 3. When this sequence switch arrives in position 5, its power magnet is energized over a circuit from grounded battery, winding of power magnet of said sequence switch, lower contacts of a sequence switch spring corresponding to sequence switch spring 36, left-hand armature and back contact of the relay corresponding to relay 32, to ground over the path described.
- 5 Under the control of this circuit, the sequence switch is moved into position 6. As soon as the sequence switch arrives in position 6, a circuit is completed from grounded battery, power magnet of such sequence switch, upper right-hand contact of a sequence switch spring corresponding to sequence switch spring 37, commutator segment 38, commutator brush 39 to ground, for moving this sequence switch into its
- 10 first or normal position.
- Returning now to the regular operation of the system, when sequence switch 29 arrives in position 2, a circuit is completed from grounded battery (Fig. 6), right-hand winding of relay 40, conductor 41, upper contacts of sequence switch spring 42, conductor 43, lower right and upper left contacts of sequence switch spring 35, to ground. Relay 40 is energized in this circuit and
- 15 completes a circuit from grounded battery, winding of power magnet 44 of the sequence switch associated with the cord finder, upper right-hand contact of sequence switch spring 45, right-hand armature and front contact of relay 40, to ground, for moving this sequence switch out of position 1 and into position 3. When sequence switch 44 leaves position 2, the original energizing circuit of relay 40 is broken, but this relay
- 20 remains energized over a locking circuit extending from grounded battery, right-hand winding of relay 40, conductors 41 and 46, left-hand armature and front contact of relay 40, upper contact of sequence switch spring 47, finder brush 48, conductor 49 and lower contact of sequence switch springs 50 associated with undesired selectors, to ground. It is to be remembered that only one district selector sequence
- 25 switch can be in position 2 at a given time, and therefore only the district selector with which the sender is to be associated can be seized by the cord finder. When sequence switch 44 arrived in position 3, a circuit was
- 30 completed from grounded battery, winding of updrive magnet 51, lower contact of sequence switch spring 45, right-hand armature and front contact of relay 40, to ground. This caused the cord finder brush set to be
- 35 moved upward in search of the terminals of the link circuit with which a sender is to be associated. As explained, relay 40 is maintained energized as long as the finder is passing over the terminals associated with
- 40 district selectors whose sequence switches are
- in any other position excepting position 2. When brush 48 encounters a terminal associated with the link circuit with which a sender is to be associated, the locking circuit of relay 40 is broken. This relay does not immediately deenergize, however, since an alternate holding circuit extends from grounded battery, left-hand winding of relay 40, right-hand contacts of sequence switch spring 52, commutator 53, brush 54, to ground. When brush 54 engages an insulating segment of commutator 53, at which time the finder brush set will be accurately centered on the terminals of an idle trunk, this second holding circuit for relay 40 is broken and this relay deenergizes and opens at its right-hand contact an armature the driving circuit of magnet 51, bringing the finder brushes to rest on the terminals associated with the desired district selector. When relay 40 is deenergized, a circuit is completed from grounded battery, winding of power magnet of sequence switch 44, lower left-hand contact of sequence switch spring 55, to ground at the right-hand armature and back contact of relay 40, for moving this sequence switch out of position 3 and into position 4.
- 45 When the cord finder sequence switch arrives in position 4 a circuit is completed from grounded battery, power magnet of sequence switch 29, lower right-hand contact of sequence switch spring 37, conductor 56, terminal 57, finder brush 58, conductor 59, lower left-hand contact of sequence switch spring 60, conductor 61, upper left-hand contact of sequence switch spring 62, to ground, for moving this sequence switch out of position 2 and into position 3.
- 50 With sequence switch 44 in position 4, a circuit is completed from grounded battery, right-hand winding of relay 40, upper right-hand contact of sequence switch spring 106, to ground. Relay 40 is energized and completes a locking circuit for itself from grounded battery, right-hand winding of relay 40, conductors 41 and 46, left-hand armature and front contact of relay 40, lower contact of sequence switch spring 47, brush 107, terminal 108, conductor 109, lower left-hand contact of sequence switch spring 50, to ground. The energization of relay 40 completes a circuit from grounded battery, power magnet of sequence switch 44, upper right-hand contact of sequence switch spring 45, right-hand armature and front contact of relay 40, to ground, for moving this sequence switch out of position 4 and into position 5.
- 55 After the cordless operator depressed the assignment key, she depressed keys in a key set to control the registration of the desired line. Assuming that the desired substation is No. 8888 and is not on a party line, and

that the outlying office through which it may be reached from the tandem point to which connection will be extended by the automatic switches is represented by the code number 323, the operator will then depress the tandem hundreds key No. 3, a tandem tens key No. 2 and a tandem units key No. 3, a key No. 8 in each of the thousands, hundreds, tens and units columns, respectively, and will also depress the start key 63, since no stations impulses are to be sent.

If the outlying office to be reached is one to which a great many calls are to be made, it may be possible to accomplish the tandem registration by depressing a single district key indicated at 64, it being observed, as will appear presently, that the depression of this single key will have the same effect on the registers controlling the outlying office selection as the depression of the tandem hundreds, tens and units keys Nos. 3, 2, 3, respectively.

Assuming that the upper allotter 153 shown in Fig. 6 is standing in position 1 to assign the sender shown in the accompanying drawings, the operation of setting the registers is as follows. As soon as the tandem hundreds key No. 3 is depressed, a circuit 25 is completed from grounded battery (Fig. 7), conductor 65, winding of relay 66, winding of relay 67, closed contacts of tandem hundreds key No. 3, winding of relay 68, conductor 69, conductor 70, upper right-hand contact of sequence switch spring 71, winding of relay 72, conductor 73, upper left-hand contact of sequence switch spring 74, to ground. Relays 66, 67, 68 and 72 are energized in this circuit, relay 72 locking 30 itself to ground at its left-hand armature and front contact. In response to the closure of tandem tens key No. 2, a circuit is completed from grounded battery conductors 65, 75 and 76, closed contacts of tandem tens key No. 2, winding of relay 77, conductor 69, to ground over the path described. In response to the operation of tandem units key 35 No. 3, a circuit is completed from grounded battery, conductor 78, winding of relay 79, closed contacts of tandem units key No. 3, conductors 80 and 69, to ground over the path described. It is thus apparent that in response to the setting up of the number 323 on the tandem keys or the depression 40 of district key 64, relays 66, 68, 67, 77, 79 and 72 have been energized. The energization of start relay 66 completed parallel circuits for the power magnets of the sequence switches controlling the class, district brush, district group, office brush and office group registers, respectively, it being borne in mind that the cord finder sequence switch is at this time in position 5. The circuit of the class register power magnet 45 may be traced from ground at the armature

and front contact of relay 66, right-hand armature and back contact of relay 81, power magnet of class register sequence switch 82, conductor 83, upper left-hand contact of sequence switch spring 84, to 70 grounded battery. The circuit of the power magnet of the district brush register may be traced from ground at the armature and front contact of relay 66, right-hand armature and back contact of relay 85, power 75 magnet 86, conductor 87, upper right-hand contact of sequence switch spring 88, to grounded battery. The circuit of the district group register sequence switch may be traced from ground at the armature and 80 front contact of relay 66, right-hand armature and back contact of relay 89, power magnet 90, conductor 91, lower right-hand contact of sequence switch spring 88, to grounded battery. The circuit of the office 85 brush register sequence switch may be traced from ground at the armature and front contact of relay 66, right-hand armature and back contact of relay 92, power magnet 93, conductor 94, upper right-hand 90 contact of sequence switch spring 84, to grounded battery. The driving circuit of the office group register sequence switch may be traced from ground at the armature and front contact of relay 66, right-hand armature and back contact of relay 95, power magnet 96, conductor 97, lower right-hand contact of sequence switch spring 84, to grounded battery.

Under the influence of the above traced 100 circuits, the registers are caused to rotate from the positions they had last assumed until brought to rest under the control of the test relays 81, 85, 89, 92 and 95, respectively, associated with them. When the 105 class register reaches position 8, a circuit is completed from grounded battery, conductor 65, winding of relay 81, class register spring 98 (position 8), closed contacts of tandem hundreds key No. 3, conductors 99, 110 100, 101, 80, 69 and 70, to ground over the path described. The energization of relay 81 opens at its right-hand armature the driving circuit of power magnet 82, and this causes the class register to be brought to rest 115 in position 8. When the district brush register arrives in position 1, a circuit is completed from grounded battery, conductor 65, winding of relay 85, district brush register spring 102, closed in position 1, armature and front contact of relay 68, conductors 69 and 70, to ground over the path described. The resultant energization of relay 85 causes the district brush register to come to rest in position 1. When the district group register arrives in position 3, a circuit is completed from grounded battery, conductor 65, relay 89, district group register spring 103, closed in position 3, armature and front contact of relay 67, conduc- 125 130

tors 69 and 70, to ground over the path described, causing the district group register to come to rest in position 3. When the office brush register reaches position 2, 5 a circuit is completed from grounded battery, winding of relay 92, office brush register spring 104, closed in position 2, armature and front contact of relay 77, conductors 69 and 70 to ground. The resultant 10 energization of relay 92 causes the office brush register to come to rest in position 2. When the office group register reaches position 3, a circuit is completed from grounded battery, conductor 65, winding of relay 95, 15 office group register spring 105, closed in position 3, armature and front contact of relay 79, conductors 69 and 70, to ground as described, causing the office group register to come to rest in position 3.

20 As soon as the class and district brush registers have been set, as indicated by the energization of relays 81 and 85, cord finder sequence switch 44 is moved from position 5 to position 6 over a circuit extending from 25 grounded battery, power magnet of sequence switch 44, conductors 110, 111 and 112, upper left-hand contact of sequence switch spring 113, conductor 114, left-hand armature and front contact of relay 81, left-hand 30 armature and front contact of relay 85, to ground at the armature and front contact of relay 66. As soon as the district group register is positioned, as indicated by the energization of relay 89, cord finder sequence 35 switch 44 is moved out of position 6 and into position 7 by a circuit extending from grounded battery, power magnet of sequence switch 44, conductors 110, 111 and 112, upper right-hand contact of sequence 40 switch spring 113, conductor 115, left-hand armature and front contact of relay 89 to ground at the armature and front contact of relay 66. As soon as the office brush and office group registers have been positioned, 45 as indicated by the energization of relays 92 and 95, sequence switch 44 is moved out of position 7 and into position 8 over a circuit extending from grounded battery, power magnet of sequence switch 44, conductors 110, 111 and 112, upper right-hand 50 contact of sequence switch spring 55, conductor 116, left-hand armature and front contact of relay 92, left-hand armature and front contact of relay 95 to ground at the 55 armature and front contact of relay 66.

The method of setting the number and stations registers will now be described. As soon as start key 63 is depressed, it being understood that the stations keys are 60 so wired that if stations impulses are to be sent the depression of a stations key will perform the same starting function as the start key, a circuit is completed from grounded battery (Fig. 9), winding of relay 117, closed contacts of start key 63, con-

ductor 118, conductor 119, conductor 70, to ground as described. The energization of relay 117 completes multiple circuits for starting the number and stations registers from their last resting positions and for 70 moving them into desired positions under the control of the depressed keys. The circuit of the stations register sequence switch extends from ground, right-hand armature and front contact of relay 117, right-hand 75 armature and back contact of relay 120, power magnet 121, conductor 122, lower left-hand contact of sequence switch spring 123, to grounded battery. The circuit of the units register sequence switch may be traced 80 from ground at the right-hand armature and front contact of relay 117, right-hand armature and back contact of relay 124, power magnet 125, conductor 126, lower right-hand contact of sequence switch 85 spring 123, to grounded battery. The circuit of the tens register sequence switch may be traced from ground at the right-hand armature and front contact of relay 117, right-hand armature and back contact 90 of relay 127, power magnet 128, conductor 129, upper right-hand contact of sequence switch spring 123, to grounded battery. The circuit of the hundreds register sequence switch may be traced from ground 95 at the right-hand armature and front contact of relay 117, right-hand armature and back contact of relay 130, power magnet 131, conductor 132, lower left-hand contact of sequence switch spring 133, to grounded 100 battery. The circuit of the thousands register sequence switch may be traced from ground at the right-hand armature and front contact of relay 117, right-hand armature and back contact of relay 134, power 105 magnet 135, conductor 136, lower right-hand contact of sequence switch spring 133, to grounded battery. The number and stations registers now rotate and continue to rotate until they arrive at the positions determined by the keys depressed. When the thousands register reaches position 8, a circuit is completed from grounded battery, conductor 137, winding of relay 134, thousands register spring 138, closed 115 in position 8, closed contacts of the thousands key No. 8, conductors 119 and 70, to ground over the path described. The resultant energization of relay 134 opens the driving circuit of the power magnet 135 and the thousands register is brought to rest in position 8. By means of similar circuits, relay 130 is energized in position 8 of the hundreds register to cause this register to stop in such position. Similarly, relay 127 causes the tens register to stop in position 8 and relay 124 causes the units register to stop in position 8. When the stations register arrives in position 0, a circuit is completed from grounded bat- 120

65 125 130

- tery, winding of relay 120, stations register spring 139, closed in position 0, closed contacts of start key 63, conductor 140, normal contacts of stations key No. 1 (used to indicate the 10,000 digit when the number of the desired line is more than 10,000), conductor 119, to ground over the path described. The resultant energization of relay 120 causes the stations register to come to rest in position 0. As soon as all the number registers and stations register have been positioned, as indicated by the energization of their associated controlling relays 134, 130, 127, 124, 120 respectively, a circuit is completed for moving sequence switch 44 out of position 8 and into position 9, this circuit extending from grounded battery, power magnet of sequence switch 44, conductors 110, 111, lower right-hand contact of sequence switch spring 55, conductor 141, in series through the left-hand armatures and front contacts of the relays 134, 130, 127, 124 and 120 respectively, to ground at the right-hand armature and front contact of relay 117.
- With the cord finder sequence switch in position 9, parallel circuits are completed to the key release magnets 142, 143, 145, 146 and 147 in parallel, these circuits being traceable from grounded battery, upper left-hand contact of sequence switch spring 88, conductor 148, winding of magnet 142, to ground; also from grounded battery, lower left-hand contact of sequence switch spring 88, conductor 149, winding of magnet 147, to ground; also from grounded battery, upper left-hand contact of sequence switch spring 133, conductor 150, through the windings of magnets 143 and 145 in parallel to ground; and from grounded battery, upper right-hand contact of sequence switch spring 133, conductor 151, winding of magnet 146, to ground. The magnets 142, 143, 145, 146 and 147 control the release of all the keys which have been depressed, and these keys should now be released. If all the keys are successfully released, the locking circuit of relay 72 will be broken when the last key is released, and this relay will deenergize, completing a circuit for moving sequence switch 44 out of position 9 and into position 10, this circuit extending from grounded battery, power magnet of sequence switch 44, conductors 110, 111 and 112, lower right-hand contact of sequence switch spring 113, lower contact of sequence switch spring 152, left-hand armature and back contact of relay 72, to ground.
- With sequence switch 44 in position 10, a circuit is completed for advancing the upper allotter sequence switch 153 into a position to assign another sender. This is accomplished by means of a circuit extending from grounded battery, power magnet of sequence

switch 153, conductors 154, 155, 156, lower contacts of sequence switch spring 42, conductors 157, 158, lower contact of sequence switch spring 159, conductor 160, left-hand contacts of sequence switch spring 161 associated with the bottom allotter 163, the upper right-hand contact of spring 162, closed in the normal position of the foot clutch, to ground.

It might be well to describe at this time the interaction of the two allotters which assign senders, these allotters being of the sequence switch type, one being indicated at 153 and the other at 163. Assuming that in the beginning allotter 163 was resting in position 18 and that allotter 153 was in position 1, upon the completion of the operation up to the point described, allotter 153 will be advanced out of position 1 and into position 2, as described. In position 2 of allotter 153, a circuit is completed from grounded battery, resistance 169, upper left-hand contact of sequence switch spring 71, winding of relay 72, upper right-hand contact of sequence switch spring 159, conductor 160, to ground over the path described. If one of the three finders which is assigned by allotter 153 is idle and in a position to be assigned, relay 72 is not energized in this circuit, since it will be shunted by a circuit extending from grounded battery, resistance 169, upper and lower left-hand contacts of sequence switch spring 71, conductor 170, upper right-hand contact of sequence switch spring 74, to ground, and since relay 72 is not energized, allotter 153 will be immediately moved out of position 2 and into position 3 by means of a circuit extending from grounded battery, power magnet of sequence switch 153, conductor 154, upper contact of sequence switch spring 152, to ground at the armature and back contact of relay 72.

As long as all the cord finders are busy and until one of them is ready for allotment, as indicated by its arrival in position 18, no keys can be depressed, since relay 72 by its energization supplies battery to the release magnet conductors 148, 149, 150, 151 by way of allotter spring 171 and the right-hand armature and front contact of relay 72, and therefore no number can be set up on the operator's key set until a sender has been assigned. As soon as a sender becomes idle, relay 72 is shunted and the allotter is moved out of position 2 and into position 3, as described.

Provided that the manually operable key 164 associated with allotter 153 is in its normal position, the allotter will at once be moved out of position 3 and into position 6 by means of a circuit extending from grounded battery, power magnet of allotter 153, upper right-hand contact of sequence switch spring 165, normally closed contacts of key 164, to ground. In position 6 the

allotter assigns the next sender and after this sender has been operated, is moved into position 12 by similar circuits to those just described. After this third sender has been used, the allotter is moved into position 17 by means of circuits just described. When allotter 153 arrives in position 17, a circuit is completed from grounded battery, winding of the power magnet of allotter 163, 10 upper left-hand contact of sequence switch spring 166, lower left-hand contact of sequence switch spring 167, to ground, for moving allotter 163 out of position 18 and into position 1, whereupon it will assign its first sender which we shall refer to as the fourth sender. With allotter 163 in position 1, a circuit is completed from grounded battery, power magnet of allotter 153, lower left-hand contact of sequence switch spring 165, upper right-hand contact of sequence switch spring 168, to ground, for moving this allotter out of position 17 and into position 18, where it will rest until allotter 163 has assigned its last sender and moved into position 17, whereupon allotter 153 will be moved out of position 18 and into position 1, to reassign the first sender.

The cord finder sequence switch remains in position 18 after completing its operation and awaits reassignment. The cord finder shown in the drawing is to be allotted in position 1 of allotter 153. Therefore, with sequence switch 44 in position 18 and allotter in position 1, a circuit is completed from grounded battery, power magnet of sequence switch 44, conductors 110, 111 and 112, lower left-hand contact of sequence switch spring 113, conductor 158, lower left-hand contact of sequence switch spring 159, conductor 160, 30 left-hand contacts of sequence switch spring 161, to ground at the normal contact of the foot clutch 162. This moves sequence switch 44 into position 1 ready for operation when another district sequence switch moves into position 2. In case the allotted cord finder is busy, in which case its sequence switch will not be resting in position 18, the operation will be delayed until it arrives in some position between 9 and 18. In positions 10 to 50 17 of the cord finder sequence switch which would normally be the next to be allotted, a circuit is completed from grounded battery, power magnet of allotter 153, conductors 154, 155 and 156, lower contacts of sequence switch spring 42, conductors 157, 158, lower left-hand contact of sequence switch spring 159, to ground over the path described, which would move the allotter from position 1 to position 2, and it would then 60 advance into position 6, as described, to assign the next cord finder.

Assuming that it is desired to eliminate the senders assigned by allotter 153, these senders can be cut out of service by depressing locking key 164, it being further as-

sumed that at the time this key is depressed allotter 153 is standing in position 1. The allotter may then be moved out of position 1 as usual and will not effect the operation of the first sender. The allotter stops in position 3 and allows allotter 163 to become independent; that is, to reassign senders 4, 5 and 6. In this case, with the key 164 depressed, lamp 172 has a circuit extending from grounded battery, operated contacts of key 164, resistance 173, the normal contact of the foot clutch spring 174, resistance 175, lamp 172, to ground, but it is shunted by a path extending by way of resistance 176, conductor 177, lower right-hand contact of sequence switch spring 106, to ground. When the assigned cord finder sequence switch arrives in position 18, this shunting circuit is removed and lamp 172 is lighted. At this point the foot clutch, controlling springs 162 and 174, is operated. In this case, ground contact supplied from the lower right-hand contact of clutch spring 162 and conductor 178 to the lower right-hand contact of allotter spring 166 prevents allotter 163 from stopping in either positions 17 or 18, and therefore this allotter will keep on assigning senders Nos. 4, 5 and 6. When the foot clutch is operated, the allotter 153 associated with it is ineffective, because the ground feed at the upper right-hand contact of clutch spring 162 is open. The allotter 153 may now be revolved and any tests or repairs which it was desirable to make may be made without affecting the operation of the system. When the allotter 153 is to be again cut into service, it must be left in position 18. Key 164 may now be released and lamp 172 will not be lighted until allotter 163 is in some position included in the 105 positions 1 to 14. This circuit extends from grounded battery, normal contacts of key 164, conductor 179, upper and lower right-hand contacts of allotter spring 161, conductor 180, lower and upper contacts of allotter 110 spring 181, resistance 182, lower contact of clutch spring 174, resistance 175, lamp 172, to ground, causing the lighting of this lamp. At this time the foot clutch may be restored to its normal position, and the allotter 153 115 will be moved out of position 18 and into position 1 when allotter 163 arrives in position 17, as usual. The circuits of the locking key and foot clutch associated with allotter 163 are identical with those described for 120 allotter 153.

In case both allotters get into a position for assigning senders; that is, in case both these allotters are in a position included between positions 1 and 14, neither is effective 125 and an alarm is given. The alarm circuit extends from ground, lower left-hand and upper right-hand contacts of sequence switch spring 183, conductor 184, normal contacts of key 164, upper and lower right-hand con-

tacts of allotter spring 181, to the alarm device. Neither can be effective since in order to assign a sender the ground supply to the sequence switch of the finder to be assigned 5 must pass through the assigning position of the one allotter and through contacts of the other allotter closed in position 18 of such other allotter. For instance, if the cord finder sequence switch shown is in position 10 18 awaiting assignment, and allotter 153 is in position 1 to assign such finder, but allotter 163 is also in a position to allot a finder, that is, in some position as 1, 6 or 12, the previously traced circuit for moving sequence switch 44 out of position 18 and into 15 position 1 will be open at the left contacts of allotter spring 161, and this allotment can therefore not be effective.

Returning now to the description of the 20 operation of the system, it is to be noted that as soon as sequence switch 44 arrived in position 6 a circuit was completed from grounded battery, power magnet of sender sequence switch 185, lower left-hand contact 25 of sequence switch spring 186, conductor 187, upper left-hand contact of sequence switch spring 188, to ground, for moving this sequence switch out of position 1 and into position 2. As soon as this has occurred, it being borne in mind that sequence 30 switch 29 is in position 3, a circuit is completed from grounded battery, right-hand winding of relay 32 (Fig. 2), upper left-hand and lower right-hand contacts of sequence switch spring 189, conductor 190, terminal 191, brush 192, conductors 193, 194, contacts of sequence switch spring 195, conductor 196, upper contact of sequence switch spring 197, conductor 198, resistance 199, 35 armature and back contact of relay 200, which is in multiple with the 0' counting relay, conductors 201, 202, upper right-hand contact of sequence switch spring 203, conductor 204, lower right-hand contact of sequence switch spring 188, to ground. Relay 32 is energized and completes a circuit 40 from grounded battery, power magnet of sequence switch 29, lower contact of sequence switch spring 30, left-hand armature and front contact of relay 32, lower right-hand and upper left-hand contacts of sequence switch spring 26, to ground, for moving this sequence switch out of position 3 and into position 5. Relay 32 in position 45 5 of sequence switch 29 has a locking circuit for itself extending from grounded battery, right-hand winding of relay 32, upper contact of sequence switch spring 34, right-hand armature and front contact of relay 32, upper and lower right-hand contacts of sequence switch spring 189, conductor 190, to ground over the path described.

With sequence switch 29 in position 5, a circuit is also completed for the updrive 50 magnet 205, this circuit extending from

grounded battery, winding of magnet 205, lower right-hand contact of sequence switch spring 34, right-hand armature and front contact of relay 32, to ground over the path described. The energization of magnet 70 205 causes a plurality of brush sets carried by shaft 206 to be moved upward in the well-known manner. The counting relays are operated in response to the upward movement of the selector brush shaft as follows. When the commutator brush 207 engages a conducting portion of commutator 208, a circuit is completed from grounded battery (Fig. 8), winding of the No. 1 counting relay, armature and back contact 80 of the No. 1' counting relay, lead 209, thence to Fig. 7, where lead 209 terminates at the upper left-hand contact of register spring 210, this contact being closed in position 1 in which this register had been set, thence 85 by conductor 211, upper right-hand contact of sequence switch spring 212, conductor 213, lower and upper contacts of sequence switch spring 214, conductor 215, upper and lower right-hand contacts of sequence switch 90 spring 216, conductors 217, 218, brush 219, terminal 220, conductor 221, contacts of sequence switch spring 222, conductor 223, commutator 208, brush 207, to ground. Counting relay No. 1 is energized and prepares in the well-known manner a circuit for the No. 1' counting relay, which relay, however, is shunted by the ground at brush 207. When brush 207 engages the first insulating segment of commutator 208, the No. 100 1' counting relay is energized. When brush 207 engages the second conducting segment of commutator 208, the No. 0 counting relay is energized, preparing circuits for the No. 0' counting relay and for relay 200. 105 When the brush 207 engages the second insulating segment of commutator 208, at which time the brush shaft 206 will have been advanced two steps, the No. 0' counting relay and relay 200 will be energized. 110 The energization of relay 200 opens at its armature and contact the circuit which has been energizing relay 32 and updrive magnet 205, and therefore, as soon as relay 200 is energized, magnet 205 is deenergized, 115 causing the brush shaft to be brought to rest with its brush sets so positioned that upon subsequent upward travel, the second brush set will be tripped into operative engagement with the group of terminals served by 120 it. The deenergization of relay 32 completed a circuit from grounded battery, power magnet of sequence switch 29, lower left and right contacts of sequence switch spring 36, left-hand armature and back contact of relay 32, lower right and upper left-hand contacts of sequence switch spring 26, to ground, for moving this sequence switch 125 out of position 5 and into position 6. At the sender, the energization of the No. 0' count- 130

ing relay completed a circuit from grounded battery, power magnet of sequence switch 185, conductor 224, armature and front contact of the No. 0' counting relay, upper left-hand contact of sequence switch spring 225, to ground, for moving this sequence switch out of position 2 and into position 3.

Provided now that the district group register has been positioned, the cord finder sequence switch 44 will have advanced to position 7 and a circuit will be completed for moving sequence switch 185 from position 3 to position 4, this circuit extending from grounded battery, power magnet of sequence switch 185, conductor 224, lower left-hand and upper right-hand contacts of sequence switch spring 226, conductor 227, lower left-hand contact of sequence switch spring 228, to ground.

As soon as sequence switch 185 arrives in position 4, the circuit for relay 32 (Fig. 2) is again completed from grounded battery, right-hand winding of relay 32, upper left and lower right contacts of sequence switch spring 189; conductor 190, terminal 191, brush 192, conductors 193, 194, contacts of sequence switch spring 195, conductor 196, upper contact of sequence switch spring 197, conductor 198, resistance 199, armature 30 and back contact of relay 200,—all the counting relays having been restored when their locking circuits were broken by the opening of the contacts of sequence switch spring 225 when sequence switch 185 moved out of position 2,—conductors 201, 202, upper right-hand contact of sequence switch spring 203, conductor 204, lower right-hand contact of sequence switch spring 188, to ground. Relay 32 is energized and at its left-

hand armature completes a circuit for moving sequence switch 29 from position 6 to position 7, this circuit being identical with that previously traced for moving this sequence switch from position 3 to position 5. As before, relay 32 completes a locking circuit for itself to conductor 193, and when sequence switch 29 arrives in position 7, a circuit for the updrive magnet 205 is again completed over the path previously described. Trip magnet 229 is energized in positions 6 to 10 of sequence switch 29 over a circuit extending from grounded battery, winding of trip magnet 229, upper left-hand contact of sequence switch spring 50, to ground, and when, in response to the energization of magnet 205, the brush shaft is again moved upwardly, the second set of brushes will be tripped.

During the group selecting operation, the operation of the counting relays is under the control of commutator brush 207 and commutator 230. When brush 207 engages the first conducting segment of commutator 230, a circuit is completed from grounded battery, winding of the No. 3 counting re-

lay (not shown), armature and back contact of the No. 3' counting relay (not shown), and thence by a lead, not shown, but terminating at the point 231 at the upper right-hand contact of the district group 70 register spring 232 (Fig. 7), thence by conductor 233, lower right-hand contact of sequence switch spring 212, conductor 213, contacts of sequence switch spring 214, conductor 215, upper and lower right-hand contacts of sequence switch spring 216, conductors 217, 218, brush 219, terminal 220, conductor 221, contact of sequence switch spring 222, conductor 223, commutator 230, brush 207, to ground. The No. 3 counting 80 relay is energized and prepares a circuit for the No. 3' counting relay in the well-known manner. The commutator 230 and brush 207 operate as described for brush selection to successively actuate the counting relays, 85 and after the brush has been advanced four group steps, the No. 0' counting relay and relay 200 will be energized as before. The relay 200 again opens the locking circuit of relay 32 and the driving circuit of magnet 90 205. The deenergization of magnet 205 brings the brush shaft to rest with the tripped set of brushes in operative relation to the fourth group of trunk terminals, and the deenergization of relay 32 moves sequence switch 29 out of position 7 and into 95 position 8 by means of a circuit similar to that utilized in moving this switch from position 5 to position 6. The energization of the No. 0' counting relay completes a circuit from grounded battery, power magnet of sequence switch 185, conductor 224, armature and front contact of the No. 0' counting relay, upper left-hand contact of sequence switch spring 225, to ground, for 100 moving this sequence switch out of position 4 and into position 5.

In position 8 of sequence switch 29 a circuit is completed from grounded battery, left-hand winding of relay 32, upper contact of sequence switch spring 234, to ground. Relay 32 is energized and completes a circuit from grounded battery, power magnet of sequence switch 29, lower contact of sequence switch spring 30, left-hand armature and front contact of relay 32, lower right and upper left-hand contacts of sequence switch spring 26, to ground, for moving this sequence switch out of position 8 and into position 9. If we assume that the terminals of busy trunks in the selected group are characterized by the presence of ground potential thereon, and if the first trunk in the selected group is busy, relay 32 completes a locking circuit for itself in position 8 extending from grounded battery, right-hand winding of relay 32, upper right-hand contact of sequence switch spring 34, right-hand armature and front contact of relay 32, lower left and upper 115 120 125 130

right contacts of sequence switch spring 35, brush 235, terminal 236, to ground, maintaining this relay energized.

With sequence switch 29 in position 9 a 5 circuit is completed from grounded battery, power magnet 205, upper right and lower left contacts of sequence switch spring 287, left-hand armature and front contact of relay 32, lower right and upper left contacts 10 of sequence switch spring 26, to ground, causing the selected brush set to be moved upward in its trunk-hunting movement. As long as brush 235 engages the terminals associated with busy trunk lines, the locking 15 circuit for relay 32 will be maintained. As soon as brush 235 encounters an open terminal indicative of an idle trunk, the circuit through brush 235 is opened. Relay 32 is, however, maintained energized a moment 20 longer over a circuit extending from grounded battery, left-hand winding of relay 32, upper contacts of sequence switch spring 33, conductor 238, commutator 239, brush 39, to ground. When brush 39 engages 25 an insulated segment of commutator 239, at which time the brushes will be accurately centered on the terminals of the desired trunk, this holding circuit will be broken and relay 32 will be deenergized, 30 opening the circuit of the updrive magnet 205 and bringing the brush set to rest on the terminals of an idle trunk leading to the desired office selector. Relay 32 upon deenergization completed a circuit from 35 grounded battery, power magnet of sequence switch 29, lower contacts of sequence switch spring 36, left-hand armature and back contact of relay 32, lower right and upper left contacts of sequence switch spring 26 to 40 ground, for moving this sequence switch out of position 9 and into position 11.

When the sender sequence switch 185 arrives in position 5, it will be immediately moved out of position 5 and into position 6 45 provided that office brush and office group registers have been positioned, in which case the cord finder sequence switch 44 will have been advanced to position 8. The circuit for moving sequence switch 185 out of position 5 and into position 6 is from grounded battery, power magnet of sequence switch 185, lower right-hand contact of sequence switch spring 186, conductor 240, upper right-hand contact of sequence switch spring 188, to ground. A circuit is now completed 50 from grounded battery, right-hand winding of relay 241 (Fig. 3), upper right and lower left contacts of sequence switch spring 242, trunk conductor 243, terminal 244, brush 245, conductor 246, upper and lower left-hand contacts of sequence switch spring 247, conductor 248, terminal 249, brush 250, conductors 251, 198, resistance 199, armature and back contact of relay 200, restored when 60 sequence switch 185 left position 4, conduct- 65

tors 201, 252, which conductor terminates in Fig. 7 at class register spring 253, thence by the upper right-hand contact of register spring 253, lead 254, terminating in Fig. 8 as the lower right-hand contact of sequence 70 switch spring 255, thence to the upper right-hand contact of sequence switch 255, conductors 256, 204, lower right-hand contact of sequence switch spring 188, to ground. Relay 241 is energized in this circuit and 75 completes a circuit from grounded battery, power magnet of sequence switch 257, upper contact of sequence switch 258, left-hand armature and front contact of relay 241, to ground, for moving this sequence switch 80 out of position 1 and into position 2. In position 2 of sequence switch 257, a circuit is completed from grounded battery, winding of updrive magnet 259, lower contact of sequence switch spring 258, to ground at the 85 left-hand armature and front contact of relay 241. Under the control of magnet 259 the office selector brush shaft 260 is moved upward in its brush-selecting operation. The counting relays are now controlled by 90 the interaction of commutator 261 and commutator brush 262. When brush 262 engages the first conducting segment of commutator 261, a circuit is completed from 95 grounded battery (Fig. 8), the No. 1 counting relay, armature and back contact of the No. 1' counting relay, lead 209, which terminates at the upper left-hand contact of office brush register 263, thence by way of conductor 264, upper left-hand contact of sequence switch spring 212, conductor 213, lower and upper contacts of sequence switch spring 214, conductor 215, upper and lower right-hand contacts of sequence switch 100 spring 216, conductors 217, 218, brush 219, terminal 220, conductor 221, lower contact of sequence switch spring 265, brush 266, terminal 267, trunk conductor 268, lower contact of sequence switch spring 269, conductor 270, commutator 261, brush 262, to 105 ground. The No. 1 counting relay is energized and prepares as before the circuit for the No. 1' counting relay, and when brush 262 engages the first insulating segment of commutator 261, the No. 1' counting relay 110 is energized. When the No. 0' counting relay and relay 200 are energized, at which time brush 262 will be engaging the second insulating segment of commutator 261, the brush shaft 260 will have made two upward steps. The energization of relay 200 opens the circuit of relay 241 which deenergizes and causes in turn the deenergization of magnet 259, thereby causing the brush shaft to be brought to rest in a 115 position such that upon the subsequent upward movement of the brush shaft, the second set of brushes will be tripped into 120 operative relation with the main section of terminals served by it. Relay 241 upon de- 125 130

energization also completes a circuit from grounded battery, power magnet of sequence switch 257, lower right-hand contact of sequence switch spring 271, left-hand armature and back contact of relay 241, to ground, for moving this sequence switch out of position 2 and into position 3.

Returning to the sender, the operation of the No. 0' counting relay completes a circuit 10 from grounded battery, power magnet of sequence switch 185, conductor 224 armature and front contact of the No. 0' counting relay, upper left-hand contact of sequence switch spring 225, to ground, for moving 15 this sequence switch out of position 6 and into position 8.

In position 3 of sequence switch 257 and position 8 of sequence switch 185, the previously traced circuit for relay 241 is reestablished, it being understood that relay 200 and the counting relays were restored when sequence switch 185 left position 6, due to the opening of the contacts of sequence switch spring 225. The energization of relay 241 at this time completes a circuit from grounded battery, power magnet of sequence switch 257, upper contact of sequence switch 258, left-hand armature and front contact of relay 241, to ground, for moving this sequence switch out of position 3 and into position 4. Relay 241 is locked in position 4 of sequence switch 257 over a circuit from grounded battery, right-hand winding of relay 241, right-hand armature and front contact of relay 241, upper and lower left-hand contacts of sequence switch spring 242, to ground over the path previously described. In position 4 of sequence switch 257, the circuit of updrive magnet 259 is again completed and is the same as previously described for the brush selecting movement. Trip magnet 272 is energized in positions 3 to 7 of sequence switch 257 over a circuit extending from grounded battery, winding of magnet 272, upper right-hand contact of sequence switch spring 273, to ground, and when, in response to the upward movement of the brush shaft 260 upon the energization of the updrive magnet 259, the brushes are again advanced, the second brush set will be released into operative relation with the section of terminals served by it.

At this time the operation of the counting relays is under the control of commutator 274 and brush 262, and when brush 262 engages the first conducting segment of commutator 274, a circuit is completed from grounded battery, winding of the No. 3 counting relay (not shown), armature and back contact of the No. 3' counting relay (not shown), to a lead terminating at the upper right-hand contact of office group register spring 275, thence by way of conductor 276, lower left-hand contact of sequence switch spring 212, conductor 213,

lower and upper contacts of sequence switch spring 214, conductor 215, upper and lower right-hand contacts of sequence switch spring 216, conductors 217, 218, brush 219, terminal 220, conductor 221, lower contact 70 of sequence switch spring 265, brush 266, terminal 267, trunk conductor 268, lower contact of sequence switch spring 269, commutator 274, brush 262, to ground. The No. 3 counting relay is energized in this circuit 75 and prepares in the well-known manner a circuit for the No. 3' counting relay, and when brush 262 engages the first insulating segment of commutator 274, the No. 3' counting relay will be energized. The successive 80 operation of the counting relays continues until the No. 0' counting relay and with it relay 200, are energized, at which time the selected brush set will have been advanced four steps. The energization of relay 200 85 opens the locking circuit of relay 241 and this relay deenergizes, causing in turn the deenergization of updrive magnet 259 and bringing the brush set to rest with the selected brush set on the bottom terminal of 90 the fourth group of trunks leading to the desired tandem point. The deenergization of relay 241 completes also a circuit from grounded battery, power magnet of sequence switch 257, lower contact of sequence switch 95 spring 271, left-hand armature and back contact of relay 241, to ground, for moving this sequence switch out of position 4 and into position 5.

In position 5 of sequence switch 257, a 100 circuit is completed from grounded battery, left-hand winding of relay 241, upper left and lower right contacts of sequence switch spring 277, to ground. Relay 241 is energized and locks up to test brush 278, provided that the first trunk in the selected group is busy and that therefore the terminal engaged by such brush has ground connected thereto. The energization of relay 241 completes a circuit from grounded battery, power magnet of sequence switch 257, upper contact of sequence switch spring 258, left-hand armature and front contact of relay 241, to ground, for moving this sequence switch out of position 5 and into position 6. In position 6 of sequence switch 257, the circuit of updrive magnet 259 is again completed by way of sequence switch 105 spring 258 to ground at the left-hand armature and front contact of relay 241. The selected brush set is again moved upward in its trunk-hunting movement and when test brush 278 encounters an open terminal associated with an idle trunk, the circuit through the right-hand winding of relay 241 is 110 broken. This relay is maintained energized an instant longer, however, over a circuit from grounded battery, left-hand winding of relay 241, upper contacts of sequence switch spring 277, conductor 279, conducting 115 120 125 130

segment of commutator 280, brush 281, to ground. When brush 281 engages an insulating segment of commutator 280, this second holding circuit for relay 241 is 5 broken and this relay deenergizes, opening the driving circuit of magnet 259 and bringing the brushes to rest, accurately centered, on the terminals of an idle trunk. The deenergization of relay 241 also completes a 10 circuit from grounded battery, power magnet of sequence switch 257, lower contact of sequence switch 271, left-hand armature and back contact of relay 241, to ground, for moving this sequence switch out of position 15 6 and into position 7.

In position 7 of sequence switch 257, relay 241 is energized over a circuit extending from grounded battery, left-hand winding of relay 241, upper left and lower right contacts of sequence switch spring 277, to ground. Relay 241 upon energization completes a circuit from grounded battery, power magnet of sequence switch 257, upper contact of sequence switch spring 258, left-hand 20 armature and front contact of relay 241, to ground, for moving this sequence switch out of position 7 and into position 8. Ground is applied to the multiples of the seized trunk to render them busy, from ground, right- 25 hand contacts of sequence switch spring 282, test brush 278, test terminal 283, to the other multiples of this trunk. Relay 241 upon energization in position 7 of sequence switch 258 locked itself over a circuit extending 30 from grounded battery, right-hand winding of relay 241, its right-hand armature and front contact, conductor 284, contacts of sequence switch spring 285, trunk conductor 286, test terminal 236, brush 235, upper contacts of sequence switch spring 35, to ground. It is to be observed that ground is applied 35 from this same source to the multiple test terminals associated with the trunk line represented at 243, 268 and 286, in order to 40 render this trunk non-selectable by other hunting district selectors.

Returning now to the sender, it will be noted that when the No. 0' counting relay and relay 200 were energized in response to 45 the last movement of the office selector, the sender sequence switch 185 was moved into position 9 by means of a circuit previously described. With the sender sequence switch in position 9, a circuit is completed from 50 grounded battery, through the winding of the No. 0 counting relay, through relay 200 and the counting relay No. 0' in parallel by way of conductor 287, upper and lower left-hand contacts of sequence switch spring 288, conductor 289, lower contact of sequence switch spring 290, lead 291 terminating at the class register in the lower left-hand contact of class register spring 292, to ground. The continued energization of the No. 0' 55 counting relay causes sequence switch 185 to

be moved through positions 9, 10 and 12 and into position 13.

As soon as sequence switch 185 arrives in position 13, provided that the number registers and the stations register have been positioned and that the keys have been released, in which case the cord finder 344 will be in position 10, a circuit is completed for moving sequence switch 185 out of position 13 and into position 1, this circuit extending 75 from grounded battery, power magnet of sequence switch 185, upper right-hand contact of sequence switch spring 186, conductor 293, lower right-hand contact of sequence switch spring 74, to ground. When sequence switch 80 185 has returned to its first or normal position, a circuit is completed for moving cord finder sequence switch 44 out of position 10 and into position 11, this circuit extending from grounded battery, power magnet of sequence switch 44, conductors 110, 111, 294, upper and lower left-hand contacts of sequence switch spring 216, conductor 295, upper left-hand contact of sequence switch spring 228, to ground.

After the office selector shown in Fig. 3 established connection to the trunk line leading to the tandem point operator's position shown in Fig. 5 and indicated generally at 0', and after sequence switch 44 had arrived 90 in position 11, it being borne in mind that sequence switch 29 is in position 11 and sequence switch 257 in position 8, a circuit is completed from grounded battery (Fig. 5), (assuming that the operator at 0' is in 100 readiness to receive a call), right-hand armature and back contact of relay 296, left-hand winding of relay 297, armature and back contact of relay 298, inner right-hand armature and back contact of relay 299, 105 trunk conductor 300, terminal 301, brush 302, lower contacts of sequence switch spring 242, trunk conductor 243, terminal 244, brush 245, conductor 246, left-hand contacts of sequence switch spring 247, conductor 248, terminal 249, brush 250, conductor 251, lower contact of sequence switch spring 197, conductors 303, 304, lower and upper left-hand contacts of impulse sequence switch spring 305, resistance 306, 110 winding of relay 307, conductor 800, lower and upper left-hand contacts of sequence switch spring 52, conductor 218, brush 219, terminal 220, conductor 221, lower contact of sequence switch spring 265, brush 266, 115 terminal 267, trunk conductor 268, upper contact of sequence switch spring 269, brush 586, terminal 308, trunk conductor 309, left-hand armature and back contact of relay 299, right-hand armature and back contact 120 of relay 298, right-hand winding of relay 297, to ground. If the operator at 0' has not yet removed the plug associated with the trunks 300 to 309 from the trunk jack 125 last used, relay 296 will be energized at this 130

time, as will appear from the subsequent description, and in this case current over the above traced path will be supplied from grounded battery through resistances 324 and 325 and right-hand armature and front contact of relay 296. When resistances 324 and 325 are included in this circuit, a test relay 307 (Fig. 8) is not energized. If, however, current is supplied from battery directly at the armature and back contact of relay 296, relay 307 is energized in the above traced circuit. Relay 297 is not energized, however, due to the presence of resistance 306 in this circuit. The energization of relay 307 completes a circuit from grounded battery, winding of relay 312, lower contact of sequence switch spring 313, armature and front contact of relay 307, to ground. Relay 312 is energized and completes a circuit from grounded battery, power magnet of impulses sequence switch 314, upper right-hand contact of sequence switch spring 315, armature and front contact of relay 312, to ground, for moving this sequence switch out of position 1 and into position 2.

In position 2 of sequence switch 314, relay 307 is energized by an alternate path which shunts out the resistance 306 extending from conductor 303, through the lower left and upper right contacts of sequence switch spring 305, winding of relay 307, and conductor 308, to the ground and battery supplies, as previously described. The shunting out of resistance 306 allows marginal relay 297 (Fig. 5) to operate. Relays 297 and 307 are energized at this time, relay 297 completing a circuit from grounded battery, winding of relay 310, armature and front contact of relay 297, to ground. Relay 310 is energized and completes a circuit from grounded battery, lamp 311, lower armature and back contact of relay 301, outer lower armature and front contact of relay 310, to ground. The lighting of lamp 311 indicates to the operator at 0' that a call is incoming over the trunk indicated by conductors 300 and 309 associated with such lamp 311. The operator at 0' upon observing the lighting of lamp 311, depresses a locking key 316, whereupon a circuit is completed from grounded battery, relay 317 (Fig. 10), conductor 318, closed contacts of key 316, winding of relay 299, to ground. Relays 299 and 317 are energized in this circuit, relay 299 operating to transfer the trunk leads 300 and 309 by way of its left-hand armature and its inner right-hand armature to conductors 319 and 320 over which impulses will be transmitted to the relay indicator device. The transferring of leads 300 and 309 to leads 319 and 320 connects both sides of the trunk to battery through the relays 321, 322 and 323, and in response to this condition relay 307 is deenergized, causing in turn the deenergization of relay 312. Re-

lay 312 upon deenergization completes a circuit from grounded battery, power magnet of sequence switch 314, upper left-hand contact of sequence switch spring 315, armature and back contact of relay 312, to ground, for moving this sequence switch out of position 2 and into position 18. Sequence switch 314 in revolving through positions 2 to 18 transmits impulses to operate the relay call indicator, as will now be described.

Whenever lead 303 (Fig. 8) is grounded by the action of the impulser springs, an impulse will be transmitted by way of the path previously described through conductor 320 and thence through relays 322 and 323 in series to grounded battery. This current flow will be designated as an impulse over the tip side of the line in order to eliminate unnecessary repetition of the tracing of the extended circuit through which such current will flow. Similarly, current flow through relay 321 and conductor 319, through conductor 800 (Fig. 8) and thence to ground at a spring of the impulser sequence switch will be known as an impulse over the ring side of the line.

With relay 317 energized, a circuit is completed from grounded battery, winding of relay 326, inner right-hand armature and back contact of relay 327, inner right-hand armature and back contact of relay 328, inner right-hand armature and back contact of relay 329, inner right-hand armature and back contact of relay 330, inner right-hand armature and back contact of relay 331, inner right-hand armature and back contact of relay 332, outer right-hand armature and back contact of relay 333, to ground at the armature and front contact of relay 317. Relay 326 is energized in this circuit and locks up over a circuit extending from grounded battery, inner left-hand armature and front contact of relay 326, inner left-hand armature and back contact of relay 334, inner left-hand armature and back contact of relay 335, inner left-hand armature and back contact of relay 336, inner left-hand armature and back contact of relay 337, inner left-hand armature and back contact of relay 338, conductors 339, 340, to ground at the armature and front contact of relay 317.

When sequence switch 314 arrives in position 2 $\frac{1}{2}$, an impulse is transmitted from grounded battery winding of relay 321, over the ring side of the line, conductors 802, 803, lower left-hand contact of district group register spring 341, closed in position 3, conductor 342, lower left-hand contact of sequence switch spring 343, to ground. Relay 321 is energized in this circuit and completes a circuit from grounded battery, right-hand winding of relay 344, winding of relay 333, inner left-hand armature and back contact of relay 344, right-hand arma-

ture and front contact of relay 321, to ground at the armature and front contact of relay 317.

The windings of relay 344 are so proportioned that its right-hand winding is not of sufficient turns to cause this relay to attract its armatures, but is of sufficient strength to maintain this relay energized after it has attracted its armatures. Relay 10 333 is energized in the circuit above traced and prepares a circuit extending from grounded battery, right-hand winding of relay 344, winding of relay 333, left-hand winding of relay 344, innermost armature 15 and front contact of relay 333, to ground. Relay 344, however, is not energized in this circuit, due to the presence of a short circuit extending through the inner left-hand armature and back contact of relay 344 and 20 the right-hand armature and front contact of relay 321, to ground.

The energization of relay 333 completes a circuit from grounded battery, winding of relay 327, inner right-hand armature and 25 front contact of relay 326, inner right-hand armatures and back contacts of relays 334, 335, 336, 337, 338, respectively, the outermost armature and front contact of relay 333, to ground. Relay 327 is energized in 30 this circuit and completes a locking circuit for itself extending from grounded battery, winding of relay 327, left-hand armature and front contact of relay 327, inner left-hand armatures and back contacts of relays 35 328, 329, 330, 331, 332, to ground by way of conductors 339 and 340.

As soon as relay 321 was energized it also completed a circuit to operate relay 345 (Fig. 12), this circuit extending from 40 grounded battery, outer left-hand armature of relay 346, left-hand winding of relay 345, conductor 347, outer right-hand armature and front contact of relay 326, conductor 348, inner right-hand armature and back 45 contact of relay 344, armature and back contact of relay 323, left-hand armature and front contact of relay 321, to ground. Relay 345 is energized and locks itself to ground through its left and right-hand windings in 50 series, its inner right-hand armature and front contact, to ground by way of conductors 349, 350 and 340.

When sequence switch 314 reaches position 2 $\frac{1}{2}$, a circuit is completed from grounded 55 battery, windings of relays 323 and 322, over the tip conductor, thence by way of conductors 351 and 352, lower left-hand contact of district group register spring 353, closed in position 3, conductor 354, lower 60 right-hand contact of sequence switch spring 343, to ground. Relay 322 is energized in this circuit and completes a circuit for relay 355 (Fig. 12), this circuit extending from grounded battery at the outer left-hand armature and back contact of relay 346, left-

hand winding of relay 355, conductor 356, outer left-hand armature and front contact of relay 326, conductor 357, outer right-hand armature and back contact of relay 344, right-hand armature and front contact 70 of relay 322, left-hand armature and front contact of relay 321, to ground. Relay 355 is energized and locks up through both its windings and its inner right-hand armature and inner right-hand front contact, to 75 grounded conductor 349. When sequence switch 314 leaves position 2 $\frac{1}{2}$, relay 321 is deenergized, and when sequence switch 314 leaves position 2 $\frac{3}{4}$, relays 323 and 322 are deenergized. When relays 321, 322 and 323 80 are deenergized, the shunt is removed from the left-hand winding of relay 344 and this relay is energized.

When sequence switch 314 reaches position 2 $\frac{3}{4}$, a circuit is completed from 85 grounded battery, windings of relays 323 and 322, over the tip conductor, thence by way of conductors 351, 352, 358, lower contact of sequence switch spring 359, to ground. Relays 322 and 323 are energized 90 in this circuit. The energization of relay 322 shunts out relay 333, but allows relay 344 to remain energized over a locking circuit extending from grounded battery, right-hand winding of relay 344, inner left-hand armature and front contact of relay 344, left-hand armature and front contact of relay 322, to ground. The shunting out of relay 333 causes this relay to deenergize, whereupon a circuit is completed from 95 grounded battery, winding of relay 334, inner right-hand armature and front contact of relay 327, through the inner right-hand armatures and back contacts of relays 328, 329, 330, 331, 332, outermost armature and back contact of relay 333, to ground. Relay 334 attracts its armatures and locks up at its inner left-hand armature and front contact over the path previously traced for locking up relay 326. It is to be observed 100 that the energization of relay 334 opens at its left-hand armature and back contact the locking circuit for relay 326, and this relay deenergizes. The energization of relays 322 and 323 does not cause an impulse to be 105 transmitted into the relay combination controlling the lighting of the number indicating lamps, since the deenergized condition of relay 321 cuts off the ground feed. When sequence switch 358 leaves position 3 $\frac{3}{4}$, relays 322 and 323 deenergize, opening the 110 locking circuit of relay 344 and allowing this relay to deenergize.

When sequence switch 314 reaches position 3 $\frac{3}{4}$, a circuit is completed from ground- 115 ed battery, winding of relay 321, over the ring conductor, thence by way of conductors 802, 359, lower contact of office brush register spring 360, closed in position 2, conductor 361, lower left-hand contact of 120

sequence switch spring 362, to ground. Relays 344 and 333 being at this time in their normal condition, the energization of relay 321 will cause as before the energization of relay 333, which prepares a circuit for relay 344. The energization of relay 333 completes a circuit from grounded battery, winding of relay 328, inner right-hand armature and front contact of relay 334, inner right-hand armatures and back contacts of relays 335, 336, 337, 338, respectively, outermost armature and front contact of relay 333, to ground. Relay 328 is energized and locks up over a locking circuit identical with that previously described for relay 327. It is to be observed that the energization of relay 328 opens the locking circuit of relay 327 and this relay deenergizes.

20 The energization of relay 321 also completed a circuit which may be traced from ground, armature and front contact of relay 317, left-hand armature and front contact of relay 321, the armature and back contact of relay 323, the inner right-hand armature and back contact of relay 344, conductor 348, conductor 363, outer left-hand armature and front contact of relay 334, conductor 364, left-hand winding of relay 365, outermost left-hand armature and back contact of relay 366, to grounded battery. Relay 365 is energized in this circuit and locks up through its right and left-hand windings and its inner right-hand armature and front contact through grounded conductor 349. When sequence switch 314 leaves position 4 $\frac{1}{2}$ relay 321 is deenergized, removing the shunt which existed about the right-hand winding of relay 344 and this relay is allowed to energize as before.

When sequence switch 314 reaches position 4 $\frac{1}{2}$, a circuit is completed from grounded battery, winding of relay 321, over the ring side of the line, thence by way of conductors 802, 367, lower right-hand contact of office brush register spring 368, closed in position 2, conductor 369, upper contacts of office group register spring 370, closed in position 3, conductor 371, lower right-hand contact of sequence switch spring 372, to ground. The resultant energization of relay 321 shunts out relay 333 and this relay deenergizes, completing a circuit from grounded battery, winding of relay 335, inner right-hand armature and front contact of relay 328, inner right-hand armatures and back contacts of relays 329, 330, 331, 332, outermost armature and back contact of relay 333, to ground. Relay 335 is energized and locks up over the locking circuit previously traced for relay 334, and at the same time opens the locking circuit of relay 334, which then deenergizes.

Relay 321 upon energization also completed a circuit from ground, armature and

front contact of relay 317, left-hand armature and front contact of relay 321, armature and back contact of relay 323, outermost left-hand armature and front contact of relay 344, conductor 373, outer right-hand armature and front contact of relay 328, conductor 374, left-hand winding of relay 375, to grounded battery. Relay 375 is energized and locks up through its left and right-hand windings, and its inner right-hand armature and front contact to grounded conductor 349. When sequence switch 314 leaves position 4 $\frac{1}{2}$ relay 321 is deenergized, causing in turn the deenergization of relay 344.

When sequence switch 314 reaches position 6 $\frac{1}{2}$, a circuit is completed from grounded battery, winding of relay 321, ring side of the line, thence by conductors 802, 376, upper contact of office brush register spring 377, closed in position 3, conductor 378, lower left-hand contact of sequence switch spring 379, to ground. Relay 321 is energized and causes the energization of relay 333. Relay 333 upon energization completes a circuit from grounded battery, winding of relay 329, inner right-hand armature and front contact of relay 335, inner right-hand armatures and back contacts of relays 336, 337, 338, outermost right-hand armature and front contact of relay 333, to ground. Relay 329 is energized and locks itself to ground over the path utilized in the locking up of relay 328, at the same time opening the locking circuit of relay 328, causing such relay to deenergize.

Relay 321 upon energization also completed a circuit from ground at the armature, and front contact of relay 317, left-hand armature and front contact of relay 321, armature and back contact of relay 323, inner right-hand armature and back contact of relay 344, conductor 348, outer left-hand armature and front contact of relay 335, conductor 380, left-hand winding of relay 381, outer left-hand armature and back contact of relay 382, to grounded battery. Relay 381 is energized and locks itself by way of its inner right-hand armature and front contact to grounded conductor 350. When sequence switch 314 reaches position 6 $\frac{1}{2}$, a circuit is completed from grounded battery, windings of relays 323 and 322, over the tip side of the line, thence by way of conductors 351, 383, lower contact of office group register spring 384, closed in position 3, conductor 385, lower right-hand contact of sequence switch spring 379, to ground. The energization of relay 322 allows a circuit to be completed from ground at the armature and front contact of relay 317, left-hand armature and front contact of relay 321, right-hand armature and front contact of relay 322, outer right-hand armature and back contact of relay 344, conductor 357, 130

- outer right-hand armature and front contact of relay 335, conductor 386, left-hand winding of relay 387, outer left-hand armature and back contact of relay 382, to 5 grounded battery. Relay 387 is energized and locks up through its inner right-hand armature and front contact to ground at conductor 350. When sequence switch 314 leaves position 6 $\frac{1}{2}$ relay 321 is deenergized, 10 and when it leaves position 6 $\frac{3}{4}$, relays 322 and 323 are deenergized. The deenergization of these relays removes the shunt from about the left-hand winding of relay 344 and this relay is energized.
- 15 When sequence switch 314 reaches position 7 $\frac{1}{2}$, a circuit is completed from grounded battery, windings of relays 323 and 322, over the tip conductor, thence by way of conductor 388, lower contact of station's register spring 389, closed in position 0, conductor 390, upper left-hand contact of sequence switch spring 391, to ground. Relays 322 and 323 are energized in this circuit, causing the shunting out of relay 333.
- 20 Relay 333 upon deenergization completes a circuit from grounded battery, winding of relay 336, inner right-hand armature and front contact of relay 329, inner right-hand armatures and back contacts of relays 330, 25 331, 332 respectively, outermost armature and back contact of relay 333, to ground. Relay 336 is energized and locks up over the circuit which has been maintaining relay 335 locked up, and at the same time opens 30 the locking circuit of relay 335, and this relay deenergizes.
- At the same time that relay 336 was energized a parallel circuit is completed from grounded battery, winding of relay 392, 40 inner right-hand armature of relay 329, to ground over the path described. Relay 392 is energized and completes a circuit from grounded battery, winding of relay 393, left-hand armature and front contact of 45 relay 392, to ground. Relay 392 upon energization establishes a holding circuit for itself through its right-hand winding by way of conductor 394 and resistance 395 to ground, this circuit having been previously ineffective, due to the shunt extending from grounded battery, through the right-hand armature and back contact of relay 392, to conductor 394. As a result of the energization of relays 392 and 393, circuits 50 are completed for the lamps which will indicate to the operator at 0' the code number of the office to which the call is to be extended, which number it will be remembered, is 323. The circuit for the tandem hundreds lamp No. 3 is completed from grounded battery, right-hand armature and front contact of relay 392, conductors 396, 397, 398, outer left-hand armature and back contact 55 of relay 399, outer left-hand armature and front contact of relay 355, inner left-hand

armature and front contact of relay 345, lamp No. 3, outer right-hand armature and back contact of relay 399, to grounded conductor 349. The circuit of the tandem tens lamp No. 2 extends from grounded battery, 7 $\frac{1}{2}$ left-hand armature and front contact of relay 393, conductors 400, 401, outer left-hand armature and front contact of relay 375, lamp No. 2, outer right-hand armature and front contact of relay 365, outer left-hand armature and back contact of relay 402, inner right-hand armature and front contact of relay 375, to grounded conductor 349. The circuit of the tandem units lamp No. 3 may be traced from grounded battery, left-hand armature and front contact of relay 393, conductor 403, outer left-hand armature and back contact of relay 404, outer left-hand armature and front contact of relay 387, inner left-hand armature and front contact of relay 381, lamp No. 3, outer right-hand armature and back contact of relay 404, to grounded conductor 350.

When sequence switch 314 leaves position 7 $\frac{1}{2}$ relays 322 and 323 are deenergized, causing the deenergization of relay 344. No impulses were transmitted to the relays controlling the stations indicating lamps, since relay 321 was not energized and therefore could not supply ground for such impulses.

When sequence switch 314 reaches position 9 $\frac{1}{2}$, a circuit is completed from grounded battery, winding of relay 321, over the ring conductor, thence by way of conductors 405, 406, lower right-hand contact of the thousands register spring 407, closed in position 8, conductor 408, lower left-hand contact of sequence switch spring 409, to ground. Relay 321 is energized, causing in turn the energization of relay 333. Relay 333 upon energization completes a circuit from grounded battery, winding of relay 330, inner right-hand armature and front contact of relay 336, inner right-hand armatures and back contacts of relays 337, 338, outermost right-hand armature and front contact of relay 333, to ground. Relay 330 is energized and locks up to ground over the path forming the locking circuit of relay 329. Relay 330 at its inner left-hand armature opens the locking circuit for relay 329, and this relay deenergizes.

Relay 321 upon energization also completes a circuit from ground at the armature and front contact of relay 317, left-hand armature and front contact of relay 321, armature and back contact of relay 323, inner right-hand armature and back contact of relay 344, conductor 348, outer right-hand armature and front contact of relay 336, conductor 410, left-hand winding of relay 411, outer left-hand armature and back contact of relay 412, to grounded battery.

When sequence switch 314 reaches position 9 $\frac{1}{2}$, a circuit is completed from grounded

battery, winding of relays 323, 322, over the tip conductor, thence by way of conductors 388, 413, upper left-hand contact of the thousands register spring 414, closed in position 8, conductor 415, upper right-hand contact of sequence switch spring 409, to ground. The energization of relay 322 completes a circuit from ground at the armature and front contact of relay 317, left-hand armature and front contact of relay 321, right-hand armature and front contact of relay 322, outer right-hand armature and back contact of relay 344, conductor 357, outer left-hand armature and front contact of relay 336, conductor 416, left-hand winding of relay 417, outer left-hand armature and back contact of relay 412, to grounded battery. Relays 411 and 417 when energized lock themselves through their inner right-hand armatures to conductor 418, which is grounded by way of conductor 340. When sequence switch 314 leaves position $9\frac{1}{2}$, relays 322 and 323 are deenergized, but since relay 321 is still energized, a circuit is completed from ground at the armature and front contact of relay 317, left-hand armature and front contact of relay 321, armature and back contact of relay 323, inner right-hand armature and back contact of relay 344, conductor 348, outer right-hand armature and front contact of relay 336, conductor 410, inner left-hand armature and front contact of relay 417, left-hand winding of relay 412, to grounded battery. Relay 412 is energized and locks up to grounded conductor 418, and opens at its outer left-hand armature the circuits of relays 411 and 417 and these relays deenergize. When sequence switch 314 leaves position $9\frac{5}{8}$, relay 321 is deenergized and allows relay 344 to become energized.

When sequence switch 314 reaches position 10, a circuit is completed from grounded battery, windings of relays 323, 322, over the tip conductor, thence by way of conductors 388, 419, lower contact of thousands register spring 420, closed in position 8, lower contacts of hundreds register spring 421, closed in position 8, conductor 422, upper right-hand contact of sequence switch spring 423, to ground. The energization of relay 322 completes at its left-hand armature a circuit for shunting out relay 333 and this relay deenergizes, whereupon a circuit is completed from grounded battery, winding of relay 337, inner right-hand armature and front contact of relay 330, inner right-hand armature and back contact of relays 331 and 332, outermost armature and back contact of relay 333, to ground. Relay 337 is energized and locks up, causing thereby the deenergization of relay 336.

When sequence switch 314 reaches position $10\frac{1}{8}$, a circuit is completed from grounded battery, winding of relay 321, over the

ring conductor, thence by way of conductors 405, 424, upper right-hand contact of thousands register spring 425, closed in position 8, contacts of hundreds register spring 426, closed in position 8, conductor 427, upper left-hand contact of sequence switch spring 423, to ground. Relay 321 is energized and completes a circuit from ground at the armature and front contact of relay 317, left-hand armature and front contact of relay 321, right-hand armature and front contact of relay 322, outer right-hand armature and front contact of relay 344, conductor 428, outer right-hand armature and front contact of relay 330, conductor 429, left-hand winding of relay 430, outer left-hand armature and back contact of relay 431, to grounded battery. Relay 430 is energized and locks up to conductor 432, which is extended to grounded conductor 418 by conductor 433. When sequence switch 314 leaves position $10\frac{1}{4}$, relays 322 and 323 are deenergized. Relay 321 is, however, maintained energized a moment longer and a circuit is completed from ground at the armature and front contact of relay 317, left-hand armature and front contact of relay 321, armature and back contact of relay 323, outer left-hand armature and front contact of relay 344, conductor 373, outer left-hand armature and front contact of relay 330, conductor 434, left-hand winding of relay 435, to grounded battery. Relay 435 is energized and locks up to grounded conductor 418. When sequence switch 314 leaves position $10\frac{5}{8}$, relay 321 is deenergized, causing in turn the deenergization of relay 344.

When sequence switch 314 reaches position $11\frac{1}{8}$, a circuit is completed from grounded battery, winding of relay 321, over the ring conductor, thence by way of conductors 405 and 436, lower left-hand contact of hundreds register spring 437, closed in position 8, conductor 438, lower left-hand contact of sequence switch spring 439, to ground. Relay 321 is energized, causing in turn the energization of relay 333. Relay 333 completes a circuit from grounded battery, winding of relay 331, inner right-hand armature and front contact of relay 337, inner right-hand armature and back contact of relay 338, outermost armature and front contact of relay 333, to ground. Relay 331 is energized and locks up, at the same time opening the locking circuit of relay 330, which deenergizes. In response to the energization of relay 321, a circuit is completed from ground at the armature and front contact of relay 317, left-hand armature and front contact of relay 321, armature and back contact of relay 323, inner right-hand armature and back contact of relay 344, conductor 348, outer right-hand armature and front contact of relay 337, conductor 440, left-hand winding of relay 441, to grounded

battery. Relay 441 is energized and locks up to grounded conductor 432 through its inner right-hand armature. When sequence switch 314 reaches position 12, a circuit is completed from grounded battery, windings of relays 323 and 322, over the tip conductor, thence by way of conductors 388 and 442, lower left-hand contact of hundreds register spring 443, closed in position 8, conductor 444, lower right-hand contact of sequence switch spring 439, to ground. Relays 322 and 323 are energized and a circuit is now completed from ground at the armature and front contact of relay 317, left-hand armature and front contact of relay 321, right-hand armature and front contact of relay 322, outer right-hand armature and back contact of relay 344, conductor 357, outer left-hand armature and front contact of relay 337, conductor 445, left-hand winding of relay 446, outer left-hand armature and back contact of relay 431, to grounded battery. Relay 446 is energized and locks up through its inner right-hand armature and front contact to grounded conductor 432. When sequence switch 314 leaves position 12 $\frac{1}{2}$, relay 321 is deenergized, and when it leaves position 12 $\frac{1}{2}$, relays 322 and 323 are deenergized, removing the shunt from about the left-hand winding of relay 344 and allowing this relay to become energized.

When sequence switch 314 reaches position 12 $\frac{2}{3}$, a circuit is closed from grounded battery, winding of relay 321, over the ring conductor, thence by way of conductors 405, 447, lower left-hand contact of tens register spring 448, closed in position 8, conductor 449, lower left-hand contact of sequence switch spring 450, to ground. Relay 321 is energized in this circuit and shunts out the winding of relay 333, as previously described, and this relay deenergizes. Upon the deenergization of relay 333, a circuit is completed from grounded battery, right-hand winding of relay 338, inner right-hand armature and front contact of relay 331, inner right-hand armature and back contact of relay 332, outermost armature and back contact of relay 333, to ground. Relay 338 is energized and locks up, opening the locking circuit of relay 337, which relay deenergizes.

As soon as relay 338 attracts its armatures, a circuit is completed from grounded battery, right-hand winding of relay 451, conductor 452, inner left-hand armature and front contact of relay 338, to ground. Relay 451 attracts its armatures and is maintained energized by a holding circuit extending from grounded battery, through the left-hand winding of relay 451, resistance 453, to ground. This circuit was previously in existence, but the left-hand winding of relay 451 will not cause this relay to attract its armatures although being of sufficient ampere turns to maintain this relay ener-

gized after its armatures have been attracted.

The energization of relay 451 controls the lighting of the thousands and hundreds digit indicating lamps. As soon as this relay attracts its armatures, a circuit is completed from grounded battery, inner right-hand armature and front contact of relay 451, conductor 454, lamp No. 8 in the thousands group, inner left-hand armature and front contact of relay 412, outer armature and back contact of relay 411, outer left-hand armature and back contact of relay 417, inner right-hand armature and front contact of relay 435, to grounded conductor 418. At the same time a circuit is completed from grounded battery, outer right-hand armature and front contact of relay 451, conductor 455, inner left-hand armature and front contact of relay 441, lamp No. 8 in the hundreds group, inner left-hand armature and front contact of relay 446, outer left-hand armature and front contact of relay 430, inner right-hand armature and front contact of relay 441, to grounded conductor 432. Thousands lamp No. 8 and hundreds lamp No. 8 are lighted in these circuits and remain lighted until the operator releases the number indicator. The lighting of these lamps informs the operator at 0' that the first two digits of the wanted line are 8-8.

Relay 321 when energized by the arrival of sequence switch 314 in position 12 $\frac{2}{3}$ over the previously traced circuit, also completes a circuit from ground at the armature and front contact of relay 317, left-hand armature and front contact of relay 321, armature and back contact of relay 323, outer left-hand armature and front contact of relay 344, conductor 373, outer left-hand armature and front contact of relay 331, conductor 456, left-hand winding of relay 457, outer left-hand armature and back contact of relay 458, to grounded battery. Relay 457 is energized in this circuit and locks itself to conductor 459 which terminates in ground by way of conductor 433. When sequence switch 314 reaches position 12 $\frac{1}{2}$, relays 323 and 322 are energized over a circuit extending from grounded battery, winding of relays 323 and 322, over the tip conductor, thence by way of conductors 388 and 460, upper contact of tens register spring 461, conductor 462, upper right-hand contact of sequence switch spring 450, to ground. An impulse is now transmitted from ground, armature and front contact of relay 317, left-hand armature and front contact of relay 321, right-hand armature and front contact of relay 322, outer right-hand armature and front contact of relay 344, conductor 428, outer right-hand armature and front contact of relay 331, conductor 463, left-hand winding of relay 464, outer left-hand armature and back contact of relay 458, to

grounded battery. Relay 464 is energized and locks up to grounded conductor 459. When sequence switch 314 leaves position 12 $\frac{1}{4}$, relays 322 and 323 are deenergized and an impulse is transmitted from ground, 5 armature and front contact of relay 317, left-hand armature and front contact of relay 321, armature and back contact of relay 323, outer left-hand armature and front 10 contact of relay 344, conductors 373, 456, inner left-hand armature and front contacts of relay 464, left-hand winding of relay 458, to grounded battery. Relay 458 is energized and locks up to grounded conductor 459. 15 Relay 458 on energizing opens at its outer left-hand armature the holding circuit of relays 457 and 464 and these relays deenergize. When sequence switch 314 leaves position 12 $\frac{1}{4}$, relay 321 is deenergized, causing 20 in turn the deenergization of relay 344.

When sequence switch 314 reaches position 13 $\frac{1}{4}$, a circuit is completed from grounded battery, winding of relays 323, 322, over the tip conductor, thence by way of conductors 388, 465, lower left-hand contact of tens 25 register spring 466, closed in position 8, conductor 467, left-hand contacts of units register spring 468, closed in position 8, conductor 469, upper right-hand contact of sequence switch spring 470, to ground. Relays 322 and 323 are energized in this circuit and cause the energization of relay 333. The energization of relay 333 completes a 30 circuit from grounded battery, winding of relay 332, inner right-hand armature and front contact of relay 338, outermost armature and front contact of relay 333, to ground. Relay 332 is energized and locks up to ground, causing in turn the deenergization 35 of relay 331. When sequence switch 314 reaches position 13 $\frac{3}{4}$, a circuit is completed from grounded battery, winding of relay 321, over the ring conductor, thence by way of conductors 405 and 471, to the 40 lower right-hand contact of tens register spring 472, closed in position 8, left-hand contacts of units register spring 473, closed in position 8, conductor 474, upper left-hand contact of sequence switch spring 470, to ground. The resultant energization 45 of relay 321 completes a circuit from ground at the armature and front contact of relay 317, left-hand armature and front contact of relay 321, right-hand armature and front 50 contact of relay 322, outer right-hand armature and back contact of relay 344, conductor 357, outer left-hand armature and front contact of relay 338, conductor 475, left-hand winding of relay 476, to grounded 55 battery. Relay 476 is energized and locks up to ground at conductor 477. When sequence switch 314 leaves position 13 $\frac{1}{2}$, relays 322 and 323 are deenergized and an impulse is sent from the armature and front 60 contact of relay 317, left-hand armature and

front contact of relay 321, armature and back contact of relay 323, inner right-hand armature and back contact of relay 344, conductor 348, outer right-hand armature and front contact of relay 338, conductor 478, 70 left-hand winding of relay 479, to grounded battery. Relay 479 is energized and locks up to grounded conductor 459. When sequence switch 314 leaves position 13 $\frac{3}{4}$, relay 321 is deenergized, allowing relay 344 to be 75 come energized.

When sequence switch 314 reaches position 14 $\frac{1}{4}$, a circuit is completed from grounded battery, winding of relay 321, over the ring conductor, thence by way of conductors 405, 480, lower left-hand contact of units register spring 481, conductor 482, lower left-hand contact of sequence switch spring 483, to ground. Relay 321 is energized in this circuit and causes the deenergization 85 of relay 333. Relay 333 upon deenergization completes a circuit from grounded battery, middle armature and back contact of relay 333, conductor 484, the windings of relays 485 and 486 in parallel, conductor 90 487, inner right-hand armature and front contact of relay 332, outermost armature and back contact of relay 333, to ground. Relays 485 and 486 are energized in this 95 circuit and are locked to ground by way of the outer right-hand armature and front contact of relay 485, conductor 488, to grounded conductor 350. A circuit for relay 489 from grounded battery, winding of relay 489, to ground over the path described 100 also exists at this time, but relay 489 is not energized, since it is shunted by direct battery on the middle armature and back contact of relay 333. Relays 485 and 486 control the lighting of the tens and stations 105 indicating lamps, as will presently be described.

Relay 321 upon energization causes an impulse to be transmitted from ground at the armature and front contact of relay 317, 110 left-hand armature and front contact of relay 321, armature and back contact of relay 323, outer left-hand armature and front contact of relay 344, conductor 373, outer left-hand armature and front contact of relay 332, conductor 490, left-hand winding of relay 491, outer left-hand armature and back contact of relay 492, to grounded battery. Relay 491 is energized and locks up to grounded conductor 477. When sequence 120 switch 314 reaches position 15 $\frac{1}{4}$, a circuit is completed from grounded battery, windings of relays 323 and 322, over the tip conductor, thence by way of conductors 388 and 493, lower contact of tens register spring 125 494, conductor 495, lower right-hand contact of sequence switch spring 483, to ground. As a result of the energization of relays 322 and 323 an impulse is transmitted from ground at the armature and front 130

contact of relay 317, left-hand armature and front contact of relay 321, right-hand armature and front contact of relay 322, the outer right-hand armature and front contact of relay 344, conductors 428, 496, outer right-hand armature and front contact of relay 332, conductor 497, left-hand winding of relay 498, outer left-hand armature and back contact of relay 492, to grounded battery. Relay 498 is energized and locks itself to grounded conductor 477. When sequence switch 314 leaves position $15\frac{3}{4}$, relay 321 is deenergized and when sequence switch 314 leaves position $15\frac{1}{2}$, relays 322 and 323 are deenergized, causing the deenergization of relay 344.

When sequence switch 314 reaches position 16, a circuit is completed from grounded battery, winding of relays 323 and 322, over the tip conductor, thence by way of conductor 499, contact of sequence switch spring 500, to ground. Relays 322 and 323 are energized, causing in turn the energization of relay 333. The energization of relay 333 removes the battery feed which has been short-circuiting the winding of relay 489 and therefore relay 489 is energized. When sequence switch 314 leaves position $16\frac{1}{2}$, relays 322 and 323 are deenergized, causing in turn the energization of relay 344 which is, however, without any effect at this time.

With the relays 485, 486 and 489 energized, circuits are completed for the No. 8 lamp in the tens group, the No. 8 lamp in the units group and the No. 0 lamp in the stations group. The circuit for the No. 8 lamp in the tens group extends from grounded battery, inner right-hand armature and front contact of relay 486, conductor 501, lamp No. 8 in the tens group, inner left-hand armature and front contact of relay 458, outer right-hand armature and back contact of relay 457, outer left-hand armature and back contact of relay 464, inner right-hand armature and front contact of relay 479, to grounded conductor 459. The circuit for the No. 8 lamp in the units group extends from grounded battery, innermost armature and front contact of relay 489, conductor 502, inner left-hand armature and front contact of relay 476, lamp No. 8, inner left-hand armature and front contact of relay 491, outer left-hand armature and front contact of relay 491, outer left-hand armature and front contact of relay 498, inner right-hand armature and front contact of relay 476, to grounded conductor 477. The circuit for the No. 0 lamp in the stations group extends from grounded battery, left-hand armature and front contact of relay 486, stations lamp 0, inner right-hand armature and back contact of relay 503, outer left-hand armature and

back contact of relay 504, outermost armature and front contact of relay 489, to ground.

When sequence switch 314 comes to rest in position 18, a circuit is completed from grounded battery, power magnet of sequence switch 29, lower right-hand contact of sequence switch spring 37, conductor 56, terminal 57, brush 58, conductor 59, upper right-hand contact of sequence switch spring 60, conductor 505, lower contact of sequence switch spring 506, conductor 507, lower contact of sequence switch spring 508, to ground for moving this sequence switch out of position 11 and into position 12. Provided that the operator at 0 has not taken down the connection by removing plug 14 from jack 13, relay 21 will still be energized over the previously traced circuit, and therefore sequence switch 29 is immediately moved out of position 12 and into position 16 by a circuit extending from grounded battery, power magnet of sequence switch 29, upper left-hand contact of sequence switch spring 37, to ground at the armature and front contact of relay 21.

As soon as sequence switch 29 leaves position 12, the locking circuit of relay 40 (Fig. 6) which extends from grounded battery, right-hand winding of relay 40, left-hand armature and front contact of relay 40, lower contact of sequence switch spring 47, brush 107, terminal 108, conductor 109 to ground at the lower left-hand contact of sequence switch spring 50, is broken. Relay 40 deenergizes and completes a circuit from grounded battery, power magnet of sequence switch 44, conductors 110, 111, lower left-hand contact of sequence switch spring 55, to ground at the right-hand armature and back contact of relay 40, for moving this sequence switch out of position 11 and into position 12.

With sequence switch 44 in position 12, a circuit is completed from grounded battery, power magnet of sequence switch 314, lower contact of sequence switch spring 315, conductor 509, upper right-hand contact of sequence switch spring 228, to ground, for moving this sequence switch out of position 18 and into its first or normal position.

As soon as sequence switch 314 reaches its normal position, a circuit is completed from grounded battery, power magnet of sequence switch 44, conductors 110, 111, 510, lower right-hand contact of sequence switch 511, conductor 512, upper contact of sequence switch spring 508, to ground, for moving this sequence switch out of position 12 and into position 15. Sequence switch 44 is then moved out of position 15 and into position 17 by a circuit extending from grounded battery, power magnet of sequence switch 44, conductors 110, 111, lower left-

hand contact of sequence switch spring 55, to ground at the right-hand armature and back contact of relay 40.

In position 17 of sequence switch 44 a circuit is completed from grounded battery, winding of downdrive magnet 513, conductor 514, upper left-hand contact of sequence switch spring 226, conductor 515, lower right-hand contact of sequence switch spring 228, to ground. Under the control of magnet 513, the cord finder brush set is returned to its normal position and upon its arrival in its normal position, a circuit is completed from grounded battery, power magnet of sequence switch 44, conductors 110, 111 and 510, lower left-hand contact of sequence switch spring 511, normal commutator segment 516, brush 54, to ground, for moving this sequence switch out of position 17 and 20 into position 18, where it remains awaiting allotment.

As soon as the operator at the tandem point has observed the lighting of all the number indicating lamps, she releases locking key 316, and the relays 299 and 317 are released. The deenergization of relay 317 causes, in turn, the release of all the locked-up relays controlling the indicator. Since the release of these relays is accomplished 30 in an obvious manner, this portion of the operation will not be described in detail.

The operator at 0' then converses with the operator at the desired outlying office by means of an order wire circuit not 35 shown. The operator at such outlying office, one of whose cords is indicated at 0'', directs the operator at 0' to use an idle trunk, and it will be assumed in this case that the operator at 0'' directs the operator 40 at 0' to use a trunk outgoing from jack 582.

It is to be observed that as soon as relay 299 was deenergized, assuming that in the meantime the district selector sequence switch has advanced to talking position 16, 45 a circuit is completed from grounded battery, right-hand armature and back contact of relay 296, left-hand winding of relay 297, left-hand armature and back contact of relay 298, inner right-hand armature and back 50 contact of relay 299, conductor 300, terminal 301, brush 302, lower contacts of sequence switch spring 242, conductor 243, terminal 244, brush 245, lower contact of sequence switch spring 25, upper winding of 55 relay 21, conductor 24, upper right-hand winding of repeating coil 22, windings of polarized relay 23, armature and front contact of relay 18, lower right-hand winding of repeating coil 22, conductor 20, winding 60 of relay 21, upper contact of sequence switch spring 19, brush 266, terminal 267, conductor 268, upper contact of sequence switch spring 269, brush 586, terminal 308, conductor 309, left-hand armature and back con-

tact of relay 299, right-hand armature and 65 back contact of relay 298, right-hand winding of relay 297, to ground. Relays 297 and 21 are energized in this circuit, but the current flow through polarized relay 23 is in such a direction as not to operate this relay. 70 The energization of relay 297 completes a circuit from grounded battery, winding of relay 310, to ground at the armature of relay 297, and in parallel a circuit is completed from grounded battery, winding of 75 relay 587, conductor 588, left-hand armature and back contact of relay 296, to ground at the armature and front contact of relay 297. Relays 310 and 587 are energized in this circuit. 80

The operator at 0', as directed, now inserts plug 581 into jack 582, whereupon a circuit is completed from grounded battery, winding of relay 296, winding of relay 801, sleeve contacts of plug 581 and jack 582, resistance 589 to ground. Relays 296 and 801 are energized in this circuit at the same time and immediately thereafter a circuit is completed from grounded battery, left-hand winding of relay 590, right-hand armature and back contact of relay 591, upper left-hand winding of repeating coil 592, tip conductors of jack 582 and plug 581, the upper armatures and front contacts of relays 801 and 310 respectively, conductor 593, 95 outer right-hand armature and back contact of relay 299, winding of supervisory relay 594, lower armature and front contact of relay 310, ring contacts of plug 581 and jack 582, lower left-hand winding of 100 repeating coil 592, left-hand armature and back contact of relay 591, right-hand winding of relay 590 to ground. Relay 594 is energized in this circuit and completes a holding circuit for relay 587 extending from 105 the armature and front contact of relay 594, the left-hand armature and front contact of relay 296, to ground at the armature and front contact of relay 297. The energization of relay 296 upon the insertion of the 110 plug into the jack prepared a circuit for current reversing relay 298, but due to the energized condition of relay 587 the upper branch of the circuit of relay 298 is broken, and the lower branch is broken at the armature of relay 594, since relay 594 is designed 115 to operate more quickly than relay 298, so that relay 298 cannot be energized at this time.

The energization of relay 590 completes 120 a circuit from grounded battery, lamp 595, armature and front contact of relay 590, lower armature and back contact of relay 596, resistance 597, to ground. Lamp 595 is lighted and indicates to the operator at 125 0'' that the call has been extended to her position. She thereupon inserts her plug 598 into the multiple jack 599 of the desired

line, whereupon a circuit is completed from grounded battery, lamp 595, winding of relay 596, sleeve contacts of plug 598 and jack 599, cut-off relay 600, to ground. Relays 596 and 600 are energized in this circuit, cut-off relay 600 operating in the well-known manner to remove the control of line relay 601 from the called subscriber. Relay 596 upon energization completes a holding circuit for itself extending from grounded battery, resistance 602, lower armature and front contact of relay 596, armature and front contact of relay 590, winding of relay 596, sleeve contacts of plug 598 and jack 599, winding of cut-off relay 600 to ground. Lamp 595 is shunted out in this circuit. The operator at 0' now supplies ringing current to the line of the called subscriber in any desired manner, and when the subscriber at the called substation answers by removing his receiver from the hook, a circuit for supervisory relay 603 is completed, this circuit extending over the called line conductors in the well-known manner.

25 The energization of relay 603 completes a circuit from grounded battery, outer armature and front contact of relay 596, winding of relay 591, to ground at the armature and front contact of relay 603. Relay 591 is energized and by attracting its armatures opens the circuit previously traced for supervisory relay 594. Relay 591 in its energized condition provides a holding circuit for relay 590, including a resistance 604.

30 The supervisory relay 594 at 0' upon deenergization completes a circuit from grounded battery, winding of relay 298, armature and back contact of relay 594, armature and front contact of relay 296, to ground at the armature and front contact of relay 297. Relay 298 upon deenergization reverses the direction of current flow in the trunk circuit extending back to repeating coil 22 in an obvious manner. The current 35 when reversed flows in a direction to energize polarized relay 23 and this relay upon energization completes a circuit from grounded battery, lower right-hand winding of the repeating coil shown at 0, winding of relay 584, ring contacts of plug 14 and jack 13, lower left-hand winding of repeating coil 22, resistance 605, armature and front contact of relay 23, upper left-hand winding of repeating coil 22, tip contacts of plug 13 and jack 14, upper right-hand winding of the repeating coil shown at 0, to ground. Relay 584 is energized in this circuit and completes a circuit from grounded battery, armature and front contact of relay 584, resistance 55 585, resistance 17, sleeve contacts of plug 14 and jack 13, winding of relay 18, to ground. Lamp 15 is shunted out in this circuit and indicates to the operator at 0 that the called subscriber has answered. The

connection is now complete and the subscribers may converse. 65

During conversation the operator at 0 has supervision of the calling line in the usual manner by means of relay 606, and has supervision of the called line as follows: Should the called subscriber desire to attract the attention of an operator he would move his switchhook up and down, causing in response to such movement alternate energization and deenergization of relay 603. In response to the alternate energization and deenergization of relay 603, relay 591 would be intermittently deenergized, causing in turn the intermittent energization of relay 594. Relay 594 upon its first energization will 70 complete a circuit for slow-release relay 587, extending from grounded battery, winding of relay 587, armature and front contact of relay 594, left-hand armature and front contact of relay 296, to ground at the armature and front contact of relay 297. With relays 594 and 587 energized the circuit of relay 298 is broken and this relay deenergizes, causing current over the trunk line to be reversed, and causing relay 23 to be deenergized. 75 In response to the deenergization of relay 23 supervisory relay 584 is deenergized and allows lamp 15 to be lighted. Relay 594 may be intermittently energized to control the intermittent operation of relay 298, to 80 cause the flashing of lamp 15 to signal the operator at 0. Slow release relay 587 remains energized during the intermittent operation of relay 597, and at its upper armature opens the circuit by which the condensers 85 607 and 608 would be made to discharge into relay 594. Relay 597 at its lower armature and front contact cuts in a resistance 609 to receive the discharge of these condensers. If it were not for this operation of 90 the relay 587, the discharge of the condensers would cause relay 594 to be brought up and cause another reversal of current by the action of relay 298 and in this way the discharge of the condensers would continue the 95 intermittent energization of relays 298 and 594 indefinitely. As stated, the presence of relay 587 eliminates this difficulty. 100

After conversation is completed and the connection is no longer desired, the calling and called subscribers replace their receivers on their respective switchhooks. When the operator at 0 is informed that connection is no longer desired by the simultaneous lighting of the calling supervisory lamp 115 (not shown) and the called supervisory lamp 15, which is lighted by means of circuits previously described, she removes plug 14 from jack 13, whereupon relay 18 is deenergized. The deenergization of relay 18 allows relays 21 and 297 to be deenergized. 120

The deenergization of relay 297 causes in turn the deenergization of relay 310, where-

upon a circuit is completed from grounded battery, lamp 311, the lower armature and front contact of relay 801, outer lower armature and back contact of relay 310, to ground, 5 causing lamp 311 to be lighted, and giving the operator at 0' the signal to disconnect. The operator at 0' disconnects by removing plug 581 from jack 582, causing in turn the deenergization of relay 590, since the circuit 10 of relay 590 at this time extends through the back contacts of relay 591 over the talking conductors. The deenergization of relay 590 removes the shunt from about lamp 595 and this lamp is lighted to give the operator at 15 0'' the signal to disconnect. The operator at 0'' disconnects by removing plug 598 from jack 599.

Before proceeding with the disconnection of the district and office selector switches, 20 it might be well to describe the sequence of operation of the supervisory lamps at the cordless operator's position shown in Fig. 2. It will be remembered that upon the first energization of relay 21 lamp 27 was caused 25 to light to indicate that a call was incoming over the trunk associated with such lamp. When the district sequence switch moves into position 2, lamp 27 is caused to burn steadily, but lamp 610 is made to 30 flicker over a circuit from grounded battery, lamp 610, contact of sequence switch spring 611, segment of fast interrupter 612 to ground. When sequence switch 29 leaves position 3 the white lamp 27 is extinguished. 35 Green lamp 610, however, continues to flicker until position 12 is reached, at which time white lamp 27 has a circuit extending through the left-hand contacts of sequence switch spring 26 to ground, and burns steadily. 40 In position 12 green lamp 610 burns steadily over a circuit extending from grounded battery, lamp 610, lower left-hand and upper right-hand contacts of sequence switch spring 189, lower and upper left-hand contacts of sequence switch spring 35, 45 to ground. In position 16, which is the talking position, white lamp 27 is extinguished but green lamp 610 continues to burn steadily, this circuit extending from 50 grounded battery, lamp 610, lower left and upper right contacts of sequence switch spring 189, right-hand armature and back contact of relay 32, lower left-hand contact of sequence switch spring 234, to ground. 55 When supervisory relay 21 is deenergized a circuit is completed from grounded battery, left-hand winding of relay 32, upper right and lower left contacts of sequence switch spring 33, armature and back contact of 60 relay 21 to ground. Relay 32 attracts its armatures and completes a parallel circuit, whereby white lamp 27 and green lamp 610 are caused to flash slowly to give the cordless operator the signal to disconnect. These

circuits may be traced as follows: grounded 65 battery, lamp 27, lower contacts of sequence switch spring 26, left-hand armature and front contact of relay 32, lower contact of sequence switch spring 237, slow interrupter 616, to ground, and from grounded battery, 70 lamp 610, lower left and upper right contacts of sequence switch spring 189, right-hand armature and front contact of relay 32, lower left-hand contact of sequence switch spring 34, and slow interrupter 616 75 to ground.

The cordless operator upon noting the slow flashing of lamps 27 and 610 depresses disconnect key 613. A circuit is thereupon completed from grounded battery, power 80 magnet of sequence switch 29, lower left-hand contact of sequence switch spring 37, lower contact of key 613, to ground, for moving this sequence switch out of position 16 and into position 18. 85

With sequence switch 29 in position 18, a circuit is completed from grounded battery, winding of down-drive magnet 614, lower right-hand contact of sequence switch spring 234 to ground. The brush shaft 206 90 is restored to its normal position under the control of magnet 614 and when it reaches its normal position, a circuit is completed from grounded battery, power magnet of sequence switch 29, upper right-hand contact of sequence switch spring 37, normal commutator segment 38, commutator brush 39, to ground, for moving the sequence switch out of position 18 and into its first or normal position. 100

When the brush set including brushes 245, 266 and 236 moves off the terminals leading to the office selector shown in Fig. 3, the locking circuit of relay 241 extending by way of conductor 286 to terminal 236 is broken and 105 this relay deenergizes. A circuit is then completed from grounded battery, power magnet of sequence switch 257, lower right-hand contact of sequence switch spring 271, left-hand armature and back contact of relay 241, to ground, for moving this sequence 110 switch out of position 8 and into position 18.

With sequence switch 257 in position 18, a circuit is completed from grounded battery, winding of down-drive magnet 700, 115 lower right-hand contact of sequence switch spring 273, to ground. The brush shaft 260 is restored to its normal position under the control of magnet 700, and when it reaches its normal position, a circuit is completed 120 from grounded battery, power magnet of sequence switch 257, upper right-hand contact of sequence switch spring 271, normal commutator segment 701, commutator brush 281, to ground, for moving this sequence 125 switch out of position 18 and into its first or normal position.

All parts of the apparatus have now been

restored to their normal positions and are ready for reoperation.

If the call is to be extended to a tandem center which is reached through an inter-district office selector, that is, an office selector not located in the same exchange with the district selector, the operation of the system is as follows, assuming that the out-lying office to be reached through the tandem center is designated by the code number 976. It will also be assumed that the desired line number as before is No. 8888 and that no stations designation will be necessary. In this case the first part of the operation will be similar to that previously described, excepting that the operator controlling the district selector shown in Fig. 2 and whom we have termed the cordless operator, will depress tandem hundreds key No. 9, tandem tens key No. 7 and tandem units key No. 6 when she sets up the number. As before, this registration might be accomplished by the depression of a single district key indicated at 517 if the office is one to which a large number of calls are to be extended.

Under this condition the operation of the district sequence switch is similar to that previously described until this switch reaches position 5. The cord finder sequence switch is operated as previously described to associate the sender with the proper cord circuit and is then advanced into its successive positions in response to the completion of the various setting operations of the registers shown in Figs. 7 and 9. The operation of setting the class district brush, district group, office brush and office group registers will not be described in detail, since from the previous description it will be obvious how the depression of tandem keys Nos. 9, 7 and 6 respectively, will operate to cause the class register to stop in position 12, the district brush register to stop in position 1, the district group register to stop in position 9, the office brush register to stop in position 7, and the office group register to stop in position 6. The setting of the number and stations registers will be identical with that previously described.

Assuming now that the district sequence switch is in position 5, the cord finder sequence switch in position 10, the sender sequence switch in position 2, and that all the registers have been positioned, the district selector shown in Fig. 2 will be operated to establish connection to a trunk outgoing to an idle interdistrict office selector leading to the desired tandem center. In this case, since the district brush register is in position 1, two impulses will be sent during brush selection, and the second brush set will be tripped. In the group selecting movement of the district selector 9 impulses will be sent and the selected brush

set will be moved into operative relation with the tenth group. Trunk hunting takes place in the usual manner. Upon the completion of this trunk-hunting movement, the district selector sequence switch will be in position 11, the cord finder sequence switch in position 10 and the sender sequence switch will have moved out of position 4 in the previously described manner. The circuits of an interdistrict office selector are shown in Fig. 4, and in this case the outgoing trunk selected, and indicated by reference numerals 243 and 268, would be extended to the selector switch shown in Fig. 4 by trunk conductors 518 and 519. In this case no third conductor would be extended to the office selector.

Sequence switch 185 is moved out of position 5 in the usual manner while sequence switch 185 is in position 5, and until it leaves position 8 a circuit is completed from grounded battery, through the No. 0 counting relay, thence through the No. 0' counting relay and relay 200 in parallel, conductor 287, upper and lower left-hand contacts of sequence switch spring 288, conductor 289, upper contact of sequence switch spring 290, conductor 520, terminating in Fig. 7 at the upper left-hand contact of class register spring 521, to ground. Counting relay Nos. 0 and 0' and relay 200 are energized in this circuit, counting relay No. 0' completing a circuit from grounded battery, power magnet of sequence switch 185, conductor 224, armature and front contact of relay No. 0', upper left-hand contact of sequence switch spring 225, to ground, for moving this sequence switch into position 9.

It will be assumed that the sequence switch associated with the interdistrict office selector shown in Fig. 4 is in position 1 at the time that the district brush set is positioned on the terminals of the trunk leading to such selector. Under this assumption when the sender sequence switch 185 reaches position 9, a circuit is completed from grounded battery, winding of relay 522 (Fig. 4), upper left-hand contact of sequence switch spring 523, conductors 518, 243, terminal 244, brush 245, conductor 246, 115 left-hand contacts of sequence switch spring 247, conductor 248, terminal 249, brush 250, conductors 251, 198, resistance 199, armature and back contact of relay 200, conductor 201, conductor 252, terminating at class register spring 253 (Fig. 7), lower right-hand contact of class register spring 253 (closed in position 12), conductor 524 (terminating in a lead indicated in Fig. 8), thence over conductor 304, lower and upper left-hand contacts of sequence switch spring 305, resistance 306, winding of relay 307, conductor 525, contact of sequence switch spring 526, conductors 527, 217, 218, brush 219, terminal 220, conductor 221, lower contact 130

of sequence switch spring 265, brush 266, terminal 267, trunk conductors 268 and 519, and the lower right-hand contact of sequence switch spring 528 to ground. Relays 522 and 307 are energized in this circuit. The energization of relay 307 completes a circuit from grounded battery, winding of the No. 0 counting relay, thence by conductor 529, upper contact of sequence switch spring 313, front contact and armature of relay 307 to ground. The No. 0 counting relay is energized and prepares a circuit for the No. 0' counting relay and relay 200, but these relays are not energized due to the presence of the shunting ground at the armature and front contact of relay 307.

Referring to Fig. 4, the energization of relay 522 completes a circuit from grounded battery, right-hand winding of relay 530, conductors 531, 532, upper and lower right-hand contacts of sequence switch spring 533 to ground at the armature and front contact of relay 522. Relay 530 is energized in this circuit and completes a circuit from grounded battery, power magnet of sequence switch 534, upper contact of sequence switch spring 535, to ground at the left-hand armature and front contact of relay 530. Sequence switch 534 is moved out of position 1 and into position 3 under the control of its normal contact 536.

As soon as the sequence switch 534 leaves position 1 the energizing circuit of relay 307 is broken and this relay deenergizes and removes the shunting ground from about the windings of the No. 0' counting relay and relay 200, and these relays are energized, the 0' counting relay completing a circuit from grounded battery, power magnet of sequence switch 185, conductor 224, armature and front contact of the 0' counting relay, upper left-hand contact of sequence switch spring 225 to ground, for moving this sequence switch out of position 9 and into position 10. In position 3 of sequence switch 534, and position 10 of sequence switch 185, the fundamental circuit is established for controlling brush selection at the interdistrict office selector, this fundamental circuit including a stepping relay 537 as will now be described.

The fundamental circuit extends from grounded battery, right-hand winding of relay 530, conductor 531, lower left-hand contact of sequence switch spring 523, conductors 518, 243, terminal 244, brush 245, conductor 246, left-hand contacts of sequence switch spring 247, conductor 248, terminal 249, brush 250, conductors 251, 198, resistance 199, armature and back contact of relay 200, conductor 201, conductor 252, terminating in Fig. 7 at the lower right-hand contact of class register spring 253, lower left-hand contact of class register spring 253

conductor 538 terminating in Fig. 8 at the lower left-hand contact of sequence switch spring 255, upper left-hand contact of sequence switch spring 255, conductor 539, lower left-hand contact of sequence switch 70 spring 540, conductor 541, winding of stepping relay 537, conductors 527, 217, 218, brush 219, terminal 220, conductor 221, lower contact of sequence switch spring 265, brush 266, terminal 267, conductors 268, 75 519, lower contact of sequence switch spring 528 to ground. Relays 530 and 537 are energized in this circuit, relay 530 completing a locking circuit for itself through its right-hand armature and front contact, the lower 80 right-hand contact of sequence switch spring 523, to ground over the path described. Relay 537 upon energization completes a circuit from grounded battery, winding of the No. 3 counting relay (not shown), armature 85 and back contact of the No. 3' counting relay (not shown), thence by a conductor terminating in Fig. 7 at the upper right-hand contact of office brush register spring 541, it being remembered that the office brush 90 register has been brought to rest in position 7, conductor 264, upper left-hand contact of sequence switch spring 212, conductor 213, lower contact of sequence switch spring 214, conductor 542 to ground at the armature 95 and front contact of relay 537. The No. 3 counting relay is energized and prepares in the well-known manner a circuit for the No. 3' counting relay, which relay will be energized as soon as shunting ground is removed upon the deenergization of the stepping relay 537.

Relay 530 upon energization completed a circuit from grounded battery, magnet of sequence switch 534, upper contact of sequence switch spring 535, left-hand armature and front contact of relay 530 to ground, for moving this sequence switch out of position 3 and into position 4.

In position 4 of sequence switch 534, relay 530 maintains its locking circuit and at the same time a circuit is completed from grounded battery, winding of up-drive magnet 543, lower contact of sequence switch spring 535, left-hand armature and front contact of relay 530 to ground. The office selector brush shaft 544 is moved upward under the control of magnet 543 in its brush selecting movement. When commutator brush 545 engages the first conducting segment of commutator 546, the stepping relay is shunted out by a circuit extending from the locking circuit of relay 530 by way of the upper contact of sequence switch spring 547, conductor 548, commutator 546, commutator brush 545, conductor 548, upper left-hand contact of sequence switch spring 549 to ground. When the stepping relay is deenergized the No. 3' counting relay is allowed to energize. When the commutator 130

- brush 545 engages an insulating segment of commutator 546, stepping relay 537 is again energized and allows the No. 2 counting relay to be energized. After the brush shaft 544 has been advanced four steps the No. 0' counting relay and relay 200 are energized, relay 200 operating to permanently open the lower branch of the fundamental circuit. This causes relay 530 to be deenergized, 10 causing in turn the deenergization of up-drive magnet 543, and bringing the brush shaft 544 to rest in a position such that upon subsequent upward movement of the brush shaft, the fourth set of brushes will be tripped into operative relation with the 15 groups of terminals served by it. The No. 0' counting relay when energized completed a circuit previously described for moving sequence switch 185 out of position 10 and 20 into position 12. When sequence switch 185 leaves position 10 the locking circuits for the counting relays are broken and these relays are restored.

At the office selector the deenergization of 25 relay 530 completed a circuit from grounded battery, power magnet of sequence switch 534, lower right-hand contact of sequence switch spring 550, left-hand armature and back contact of relay 530 to ground, for moving this sequence switch out of position 4 and into position 5.

In position 5 of sequence switch 534 and position 12 of sequence switch 185, the fundamental circuit is again established as previously described, and relay 530 and stepping relay 537 are energized. The energization of relay 530 completes a circuit from grounded battery, power magnet of sequence switch 534, upper contact of sequence switch 35 spring 535, left-hand armature and front contact of relay 530 to ground, for moving this sequence switch out of position 5 and into position 6, and the energization of stepping relay 537 completes a circuit from 40 grounded battery, the winding of the No. 6 counting relay (not shown), armature and back contact of the No. 6' counting relay (not shown), thence by a conductor (not shown) terminating at the upper left-hand 45 contact of office group register spring 551, it being remembered that the office group register was brought to rest in position 6, thence by conductor 276, lower left-hand contact of sequence switch spring 212, conductor 213, 50 lower contact of sequence switch spring 214, conductor 542 to ground at the armature and front contact of relay 537.

In position 6 of sequence switch 534, the 60 circuit of updrive magnet 543 is again completed over a path previously described and the brush shaft 544 is advanced upwardly in its group selecting movement. Trip magnet 552 is energized in positions 5 to 9 of sequence switch 534 over a circuit extending 65 from grounded battery, winding of trip

magnet 552, lower right-hand contact of sequence switch spring 553, to ground, and upon upward travel of the brush shaft the fourth set of brushes will be released.

During the group selecting movement of 70 the office selector the operation of the stepping relay 537 is under the control of a commutator 554 and commutator brush 545, by means of circuits similar to those described for brush selection. Upon the 75 seventh shunting of the stepping relay, at which time the selected brush set will be resting on the bottom terminal of the seventh group of terminal sets served by it, relay 200 and the No. 0' counting relay will be 80 energized. Relay 200 opens the fundamental circuit and causes the deenergization of relay 530. Relay 530 upon deenergizing opens the circuit of up-drive magnet 543 and brings the brush shaft to rest, and at 85 the same time completes a circuit from grounded battery, power magnet of sequence switch 534, lower right-hand contact of sequence switch spring 550, left-hand armature and back contact of relay 530 to ground, for moving this sequence switch out of position 6 and into position 7. The energization of the No. 0' counting relay completes a circuit for moving sequence switch 185 out of position 12 into position 13 over 90 a path previously described. Sequence switch 185 is moved out of position 13 and into position 1, as previously described in the case in which a call was extended through a local office selector.

When sequence switch 534 reaches position 100 7, a circuit is completed from grounded battery, right-hand winding of relay 530, lower left-hand contact of sequence switch spring 553, to ground. Relay 530 is energized and locks itself to test brush 555 provided that the first trunk in the group is busy and is, therefore, characterized by the presence of ground on its multiple test terminals. This locking circuit extends from 105 grounded battery, right-hand winding of relay 530, right-hand armature and front contact of relay 530, upper contacts of sequence switch spring 578, test brush 555 and thence to ground. The energization of 110 relay 530 completes a circuit from grounded battery, power magnet of sequence switch 534, upper contact of sequence switch spring 535, left-hand armature and front contact of relay 530, to ground, for moving this 115 sequence switch out of position 7 and into position 8.

With the sequence switch 534 in position 120 8, a circuit is completed from grounded battery, winding of up-drive magnet 543, 125 lower contact of sequence switch spring 535, left-hand armature and front contact of relay 530, to ground. The selected brush set is now moved upward under the control of magnet 543, and when test brush 555 en- 130

counters a terminal 556, which has no ground potential connected thereto, due to the idle condition of its associated trunk, the locking circuit through the right-hand winding of relay 530 is broken. Relay 530 is held energized a moment longer, however, by a circuit extending from grounded battery, left-hand winding of relay 530, lower contacts of sequence switch spring 557, commutator 558, commutator brush 559, conductor 548, lower right-hand contact of sequence switch spring 549, left-hand armature and front contact of relay 530 to ground. When brush 559 engages an insulating segment of commutator 558, at which time the brush set will be accurately centered on the terminals of an idle trunk, this holding circuit is broken and relay 530 is deenergized, opening the circuit of up-drive magnet 543 and causing the brush set to be brought to rest. The deenergization of relay 530 also completes a circuit from grounded battery, power magnet of sequence switch 534, lower right-hand contact of sequence switch spring 550, left-hand armature and back contact of relay 530 to ground, for moving this sequence switch out of position 8 and into position 9. In position 9 of sequence switch 534, ground is supplied to the multiple test terminals of the trunk seized from ground, through the lower and upper right-hand contacts of sequence switch spring 578 and test brush 555 to the multiple test terminals of such trunk to render such trunk non-selectable to other hunting selectors.

In position 9 of sequence switch 534 impulses are sent to the relay call indicator to inform the operator at the tandem point, of the office to which the call is to be extended and of the line number desired in such office. Sequence switch 534 is caused to remain in position 9 for a sufficient length of time for the accomplishment of selection beyond by means of a timing arrangement which will now be described. The marginal supervisory relay 560 is designed to be similar in operation to relay 297, Fig. 5, that is, it cannot operate when the resistance 306, Fig. 8, is included in its circuit. However, when the talking circuit is connected through to the operator's position 0' over the trunk indicated at 20 and 24, relays 560 and 297 will be operated either by direct battery or direct battery supplied through resistances 324 and 325 of Fig. 5. With the sequence switch 534 in position 9, the relay 560 has its lower winding short-circuited by means of the upper contacts of sequence switch spring 528 and cannot operate. A circuit is, therefore, completed from grounded battery, winding of relay 561, lower and upper left-hand contacts of sequence switch spring 533, armature and back contact of relay 560, lower

left-hand contact of sequence switch spring 562, interrupter brush 563, conducting segment of timing interrupter 564 to ground. When this circuit is completed relay 561 completes a locking circuit for itself extending from grounded battery, winding of relay 561, lower and upper left-hand contacts of sequence switch spring 533, armature and back contact of relay 560, upper left-hand contact of sequence switch spring 562, right-hand armature and front contact of relay 561, to ground. Interrupter 564 continues its rotation and consumes in such rotation enough time to allow impulses to be sent to the relay call indicator, or, if selection is to be extended by mechanical switches, to allow these switches to be operated. After the required amount of time has been consumed and the conducting segment of interrupter 564 engages brush 565 a circuit is completed from grounded battery, right-hand winding of relay 530, conductor 531, left-hand armature and front contact of relay 561, left-hand contact of sequence switch spring 566, brush 565, conducting segment of interrupter 564 to ground. Relay 530 is energized in this circuit, and completes a circuit from grounded battery, power magnet of sequence switch 534, upper contact of sequence switch spring 535, left-hand armature and front contact of relay 530 to ground, removing this sequence switch out of position 9 and into position 11.

The operation of the relay call indicator will be similar to that previously described, excepting that in this case the tandems lamps indicate the office code number 9 7 6 to the operator at 0'. Since the method of the operation of the indicator has been fully described previously, it is thought that the manner in which the relay combination controlling the lighting of lamps 9, 7, 6 in the tandem hundreds, tandem tens and tandem units groups respectively, is set up, will be readily understood without further description.

The operator at 0' proceeds to set up a connection as before and when battery is supplied to the trunk conductors 566 and 567 the marginal relay 560 will be energized over a circuit extending from grounded battery, either through back contact of relay 296 or through resistances 324 and 325 and the front contact of relay 296, thence to the right-hand winding of relay 297, left-hand armature and back contact of relay 298, inner right-hand armature and back contact of relay 299, conductors 300 and 566, terminal 568, brush 569, upper armature and back contact of relay 570, upper winding of relay 560, conductors 518 and 243, terminal 244, brush 245, also right-hand contact of sequence switch spring 25, upper winding of relay 21, conductor 24, upper right-hand winding of repeating coil 130

22, windings of polarized relay 23, armature and front contact of relay 18, lower right-hand winding of repeating coil 22, conductor 20, lower winding of relay 21, 5 upper right-hand contact of sequence switch spring 19, brush 266, terminal 267, conductors 268 and 519, lower winding of relay 560, lower armature and back contact of relay 570, brush 571, terminal 572, conductors 567 and 309, left-hand armature and back contact of relay 299, right-hand armature and back contact of relay 298, right-hand winding of relay 297, to ground. Relays 297 and 560 are energized in this 10 circuit. The relay 560 upon energization completes a circuit from grounded battery, right-hand winding of relay 530, conductors 531 and 573, contact of sequence switch spring 702, armature and front contact of 15 relay 560, lower and upper left-hand contacts of sequence switch spring 549 to ground. Relay 530 is energized and completes a circuit from grounded battery, power magnet of sequence switch 534, upper contact of sequence switch spring 535, left-hand armature and front contact of relay 530 to ground, for moving this sequence switch out of position 11 and into position 13, which is the talking position. 20 The release of the office selector is controlled by supervisory relay 560 and this relay, upon deenergization, will cause the release of the switch. However, due to the 25 signaling between operators or the opening of the trunk line for the purpose of reringing (reringing by the opening of the trunk conductors being well known in the art), relay 560 will be caused to fall off for short intervals from time to time. In order that 30 the switch may not be released during these short intervals it has been necessary to include a timing arrangement, such that the release of the selector switch will occur only after relay 560 has remained deenergized 35 for a predetermined time interval. This occurs as follows. Upon deenergization of relay 560 a circuit is completed from grounded battery, winding of relay 561, lower and upper left-hand contacts of sequence switch spring 533, armature and back contact of relay 560, lower right-hand contact of sequence switch spring 562, brush 574, conducting segment of interrupter 575 to ground. Relay 561 is energized in this 40 circuit and locks up over a circuit extending from the upper left-hand contact of sequence switch spring 562 and right-hand armature and front contact of relay 561 to ground. If relay 560 is still deenergized when the 45 conducting segment of interrupter 575 reaches brush 576, a circuit will be completed from grounded battery, right-hand winding of relay 530, conductors 531 and 532, left-hand armature and front contact of relay 561, right-hand contact of sequence switch 50 spring 566, brush 576 and conducting segment of interrupter 575 to ground. Relay 530 energizes in this circuit and completes a circuit from grounded battery, power magnet of sequence switch 534, upper contact of sequence switch spring 535, left-hand armature and front contact of relay 530 to ground, for moving this sequence switch out of position 13 and into position 18. It is obvious that if relay 561 was energized in response 55 to the deenergization of relay 560 and that if in the meantime relay 560 becomes energized, the locking circuit of relay 561 will be broken and the energizing circuit for relay 530 cannot be completed. In this way 60 momentary deenergizations of relay 560 will not allow the selector to release. 65 If at the conclusion of conversation and in response to the continued deenergization of relay 560 sequence switch 534 is moved into position 18, the selector is restored as follows: A circuit for down-drive magnet 577 is completed from grounded battery, winding of magnet 577, lower contacts of sequence switch spring 578 to ground. Under the 70 control of magnet 577, the brush rod 544 is returned to its normal position and when it reaches its normal position, a circuit is completed from grounded battery, power magnet of sequence switch 534, upper right-hand contact of sequence switch spring 550, conductor 579, normal commutator segment 580, brush 559, conductor 548, upper left-hand contact of sequence switch 549, to ground, for moving this sequence switch out of position 18 and into its first or normal position. 75 It has been pointed out that it is necessary to provide a time interval after the deenergization of relay 560 before the office selector is restored to normal in order to prevent false disconnection due to signaling or reringing. Due to this condition, however, the same time interval is required after the trunk indicated at 518 and 519 has been released by the district selector. Therefore, 80 unless special means are provided, it might be possible for another district selector to seize this trunk line before the office selector had been restored and was in condition for reoperation. In the present arrangement it is 85 possible for another district selector to seize the office selector shown, but no false impulses would be sent, due to an arrangement which will now be described. 90 It will be assumed that the district selector shown in Fig. 2 has placed its brushes 95 245 and 266 on the terminals leading to the office selector shown in Fig. 4 and that the sequence switch associated with this office selector is standing in position 13. At this time, the cord finder sequence switch 44 will be in position 11 and the sender sequence switch 185 will have been advanced to position 9. At this time the test relay 307, Fig. 8, is included in the circuit of relays 560 100 105 110 115 120 125 130

and 297 and in series with such relay 307 is the resistance 306. This circuit extends (assuming that the operator at 0' has disconnected and that plug 581 has been removed from jack 582), from grounded battery, right-hand armature and back contact of relay 296, left-hand winding of relay 297; left-hand armature and back contact of relay 298, inner right-hand armature and back contact of relay 299, conductors 300 and 566, terminal 568, brush 569, lower contacts of sequence switch spring 583, upper winding of relay 560, lower right-hand contact of sequence switch spring 547, conductors 518 and 243, terminal 244, brush 245, conductor 246, left-hand contacts of sequence switch spring 247, conductor 248, terminal 249, brush 250, conductor 251, resistance 199, armature and back contact of relay 200, conductor 201, conductor 252 terminating in Fig. 7 at class register spring 253, lower right-hand contact of class register spring 253, conductor 524 terminating in Fig. 8, conductor 304, lower and upper left-hand contacts of sequence switch spring 305, resistance 306, winding of relay 307, conductor 525, contact of sequence switch spring 526, conductors 527 and 217, 218, brush 219, terminal 220, conductor 221, lower contact of sequence switch spring 265, brush 266, terminal 267, conductors 268 and 519, upper left-hand contact of sequence switch spring 528, lower winding of relay 560, upper contacts of sequence switch spring 557, brush 571, terminal 572, conductors 567 and 309, left-hand armature and back contact of relay 299, right-hand armature and back contact of relay 298, right-hand winding of relay 297 to ground. Due to the presence of resistance 306, relays 560 and 297 are not energized in this circuit and relay 560 remains deenergized and allows the sequence switch 534 to move out of position 13, as previously described. Relay 307 is energized in this circuit, however, and completes an energizing circuit for the No. 0 counting relay, as previously described.

When sequence switch 534 reaches position 14, a circuit is completed from ground battery, winding of relay 570, upper contacts of sequence switch spring 583, to ground. Relay 570 attracts its armatures and a circuit is completed from grounded battery, winding of relay 522, upper armature and front contact of relay 570, upper winding of relay 560, trunk conductor 518, thence over the path described and including relay 307, and returning by way of conductor 519, upper left-hand contact of sequence switch spring 528, lower winding of relay 560 to ground at the lower armature and front contact of relay 570. This circuit maintains relay 307 energized. Relay 522 is

energized and when sequence switch 534 reaches position 1, the energized condition 65 of relay 522 causes the energization of relay 530, as previously described, and sequence switch 534 moves out of position 1 and into position 3. When sequence switch 534 leaves position 1, relay 307 is deenergized and allows the No. 0' counting relay to be energized to move the sequence switch out of position 9 and into position 10 to allow the sender to transmit impulses, when the fundamental circuit is closed upon the 75 arrival of sequence switch 534 in position 3.

If the operator at 0' had not yet removed plug 581 from jack 582 battery would have been supplied through resistances 324 and 325 to relay 307, when the district selector 80 seizes the terminals of the office selector. In this case relay 307 would not have been energized, but since relays 297 and 560 are also not energized the office selector would have proceeded to disconnect, as described. In 85 this case relay 307 would have been energized when the office selector reached position 14, and relay 570 was energized. It is obvious, however, that the sender sequence switch 185 cannot be moved into position 10 90 to start transmitting impulses until the office selector has been fully restored and its associated sequence switch has advanced to a position suitable for the reception of impulses. 95

It is to be observed also that the class register controls the introduction of stepping relay 537 into the fundamental circuit. For instance, when the class register is in position 8, in which case a local office selector is to be used, the sender sequence switch stops in positions 4 and 6 to transmit impulses to the local office selector. However, when the class register is in position 12, 100 positions 6 and 8 are skipped and the sender 105 sequence switch is moved into position 10, and then into position 12, to control selection at an inter-district office selector.

The sequence of operations which take place when all the trunks of a selected group are busy at any of the selector switches will now be described. In this case the operator at 0 will be informed of this condition by the flashing of her calling supervisory lamp and the presence of a special tone on the line, this tone being differentiated from that supplied when a busy signal is to be transmitted. 110

It will be assumed that all the trunks of a group at the district selector shown in 120 Fig. 2 are busy. In order to outline the operations which take place it will further be assumed that the call was to have been extended through a local office selector such as shown in Fig. 3. Under this assumption, 125 sequence switch 29 will be in position 9,

sequence switch 44 will be in position 10 and sequence switch 185 will have moved from position 4 upon the completion of group selection and will have been advanced 5 into position 6 as previously described.

With sequence switch 29 in position 9, the brush carrying rod 206 of the district selector will be moved upward in its trunk hunting movement. Since all the trunks 10 in the selected group are busy, test brush 235 will continue to engage grounded test terminals and relay 32 will remain energized. After all the trunk terminals have been passed over, the brush set will encounter 15 a terminal set leading to overflow apparatus, indicated in Fig. 3, over conductors 243' and 268'. The test terminal 236 associated with such lines is ungrounded and when overflow apparatus is encountered, test relay 32 will be deenergized, causing the brush shaft to be brought to rest and causing sequence switch 29 to be moved 20 out of position 9 into position 11.

A circuit is now completed from ground, 25 positive pole of battery, winding of relay 617, conductor 243', conductor 243, terminal 244, brush 245, conductor 246, left-hand contacts of sequence switch spring 247, conductor 248, terminal 249, brush 250, conductors 251, 198, resistance 199, armature and back contact of relay 200, conductor 201, conductor 252, terminating at the class register spring 253 in Fig. 7, upper right-hand contact of class register spring 253, conductor 30 254, terminating in Fig. 8 at lower right-hand contact of sequence switch spring 255, upper right-hand contact of sequence switch spring 255, conductor 256, conductor 204, lower right-hand contact of sequence switch 35 spring 188 to ground. This circuit includes in parallel with the resistance 199, the left-hand winding of a relay 618. It is to be noted that with sequence switch 185 in position 40 6, a circuit through the right-hand winding of relay 618 extends from ground to battery, right-hand winding of relay 618, resistance 619, lower right-hand contact of sequence switch spring 62 to ground. This winding of relay 619 operates to polarize 45 50 this relay, but is not of sufficient strength to cause its energization. During the normal operation of the system current flow over conductor 198 through resistance 199 and armature and back contact of 200 is in such a direction that relay 618 is not energized, since the current flow through its 55 left-hand winding is in such a direction as to cause this winding to magnetically oppose the right-hand winding. However, 60 when battery is supplied to conductor 198 from the positive pole of battery (instead of from the negative pole of battery as is always the case while the fundamental circuit is established), the current flow 65 through the left-hand winding of relay 618

is in such a direction that this relay will be energized. Relay 618 upon energization completes a circuit from grounded battery, winding of relay 620, armature and front contact of 618 to ground. Relay 620 upon 70 energization completes a locking circuit for itself extending from grounded battery, winding of relay 620 right-hand armature and front contact of this relay, conductor 621, lower left-hand contact of sequence 75 switch spring 74 to ground. Relay 620 upon energization completes at its left-hand armature a holding circuit for relays 618 and 617 and also completes a circuit from 80 grounded battery, power magnet of sequence switch 29, lower right-hand contact of sequence switch spring 37, conductor 56, terminal 57, brush 58, conductor 59, upper right-hand contact of sequence switch 85 spring 60, conductor 505, left-hand armature and front contact of relay 620 to ground. The completion of this circuit causes sequence switch 29 to move out of 90 position 11 and into position 12. If the operator at 0 has not disconnected, relay 21 95 will be energized and sequence switch 29 will be moved out of position 12 and into position 16 over a circuit extending from grounded battery, power magnet of sequence switch 29, upper left-hand contact of 100 sequence switch spring 37, armature and front contact of relay 21 to ground. When sequence switch 29 arrives in position 16, it is immediately moved into position 17 by a circuit extending from grounded battery, 105 power magnet of sequence switch 29, lower right-hand contact of sequence switch spring 37, conductor 56, terminal 57, brush 58, conductor 59, upper right-hand contact 110 of sequence switch spring 60, conductor 505 to ground at the right-hand armature and front contact of relay 620.

It will be remembered that in the normal operation of the system, when sequence switch 29 leaves position 12, the locking circuit of relay 40, Fig. 6, which extends from grounded battery, right-hand winding of relay 40, conductor 46, left-hand armature and front contact of relay 40, lower contact of sequence switch spring 47, brush 115 107, terminal 108, conductor 109, lower left-hand contact with sequence switch 50 to ground, is broken, and relay 40 is deenergized to move sequence switch 44 out of position 10 and into position 11. However, 120 in the present case, when all the trunks in the selected group are busy and with the relay 620 energized, relay 40 maintains its locking circuit, which circuit now extends from conductor 109 to the upper contact 125 of sequence switch spring 621, thence by conductor 248, terminal 249, brush 250, conductors 251 and 198, resistance 199 to ground at the left-hand armature and front contact of relay 620. Due to the continu- 130

ance of this locking circuit for relay 40, the premature release of the cord finder is prevented and the completion of the circuit for moving sequence switch 29 out of position 16 and into position 17 is assured.

When sequence switch 29 leaves position 16, the locking circuit of relay 40 is broken and this relay deenergizes, and completes a circuit from grounded battery, power magnet of switch 44, conductors 110, 111, lower left-hand contact of sequence switch spring 55, right-hand armature and back contact of relay 40 to ground, for moving the sequence switch out of position 10 through position 11, and into position 12. A circuit is then completed from grounded battery, power magnet of sequence switch 44, conductors 110, 111, 510, lower right-hand contact of sequence switch 511, conductor 512, upper contact of sequence switch spring 508 to ground, for moving this sequence switch out of position 12 and into position 15. A circuit is then completed from grounded battery, power magnet of sequence switch 44, conductors 110, 111, lower left-hand contact of sequence switch spring 55, right-hand armature and back contact of relay 40 to ground, moving the sequence switch 44 out of position 15 and into position 17.

With sequence switch 44 in position 17, a circuit is completed from grounded battery, power magnet of sequence switch 185, conductor 224, lower left-hand contact of sequence switch spring 226, conductor 515, lower right-hand contact of sequence switch spring 228 to ground, for moving sequence switch 185 out of position 6 and into position 1. A circuit is then completed from grounded battery, down-drive magnet 513, conductor 514, upper left-hand contact of sequence switch spring 226, conductor 515, lower right-hand contact of sequence switch spring 228 to ground. The cord finder is restored under the control of down-drive magnet 513 and when it reaches normal position, sequence switch 44 is advanced out of position 17 and into position 18 as previously described, and then remains in position 18 awaiting allotment. The sender and cord finder have now been completely restored and are ready for re-use.

With sequence switch 29 in position 17, a circuit is completed from grounded battery, lower winding of relay 622 (shown in the dotted rectangle, Fig. 2), left-hand contact of sequence switch spring 623, lower left-hand contact of sequence switch spring 19, lower winding of relay 21, conductor 20, lower right-hand winding of repeating coil 22, armature and front contact of relay 18, winding of polarized relay 23, upper right-hand winding of repeating coil 22, conductor 24, upper winding of relay 21, upper left-hand contact of sequence switch spring

25, lower right-hand contact of sequence switch spring 624, upper winding of relay 622 to ground. Relay 622 is energized in this circuit and completes a circuit from grounded battery, power magnet of sequence switch 625, lower contact of sequence switch spring 626, armature and front contact of relay 622 to ground. Sequence switch 625 is started in rotation and moves through a complete cycle of positions and back into position 1 under the control of its normal contact 627. As soon as sequence switch 625 reaches position 1 $\frac{1}{4}$, a circuit is completed from grounded battery through interrupter 628, primary winding of induction coil 629, and the contact of sequence switch spring 630 to ground. A current is induced in the secondary winding of coil 629 to superimpose a tone over the line, to the operator at 0, this circuit extending through the upper contact of sequence switch spring 25 over the line in an obvious manner. When sequence switch 625 leaves position 9, the direction of current flow through the relay 23 is reversed and current now flows from grounded battery, winding of relay 622, lower left-hand contact of sequence switch spring 624, over the upper side of the line, returning over the lower side of the line and thence to the upper right-hand contact of sequence switch spring 623 and the upper winding of relay 622 to ground. Relay 622 remains energized but the current reversal causes polarized relay 23 to be operated to light the supervisory lamp 15 at the operator's position 100 at 0. After sequence switch 625 has completed a complete cycle of operations, if the sequence switch 29 is still in position 17, the continued energization of relay 622 will cause sequence switch 625 to be started on 105 another revolution. The reversal of current over the line causes the intermittent lighting of lamp 15 and when the operator at 0 listens-in to determine what is wanted, she will hear the special overflow tone and will 110 thereupon remove plug 14 from jack 13, causing the deenergization of relay 21. The deenergization of relay 21 completes a circuit from grounded battery, left-hand winding of relay 32, upper right-hand and lower 115 left-hand contacts of sequence switch spring 33, armature and back contact of relay 21 to ground. Relay 32 is energized in this circuit and completes circuits similar to those used in the case of ordinary disconnection and 120 causes the slow flashing of white lamp 27 and green lamp 610. The circuit of lamp 27 may be traced from grounded battery, lamp 27, lower contacts of sequence switch spring 26, left-hand armature and front contact of relay 32, lower and upper left-hand contacts of sequence switch spring 237, slow interrupter 616 to ground. The circuit of lamp 610 may be traced from grounded battery, lamp 610, lower left and upper 125

right-hand contacts of sequence switch spring 189, right-hand armature and front contact of relay 32, lower left-hand contact of sequence switch spring 34 and slow inter-
rupter 616 to ground. The flashing of lamps 610 and 27 informs the cordless operator that connection is no longer desired and she presses disconnect key 613, causing the restoration of the district selector as pre-
10 viously described.

It is to be observed that when the selected brush set is brought to rest on the set of over-
flow terminals, the resultant energization of
15 relay 617 completes a circuit from grounded
battery, magnet 631 (Fig. 3), armature and
front contact of relay 617 to ground. Magnet 631 operates a step-by-step counting de-
vice of any desired type, which is utilized to
record the number of times that the over-
20 flow condition occurs in any given group of
trunks.

The manner in which the overflow condition is handled at the office selectors, either local or inter-district, is substantially simi-
25 lar to that described, and it is thought may be readily understood without further de-
scription.

What is claimed is:

1. In a telephone exchange system, a
30 plurality of groups of automatic switches, a series of allotter switches, there being an allotter switch individual to each group, means to operate one of said allotter switches to successively bring into service
35 desired ones of the automatic switches controlled by it, means to operate said allotter switches in succession, and means to reop-
erate the first allotter switch of said series upon the completion of the operation of the
40 last allotter switch of said series.

2. In a telephone exchange system, a plurality of groups of automatic switches, an allotter switch individual to each group of automatic switches, means to operate an
45 allotter switch to successively bring into service desired ones of the automatic switches controlled by it, means operative after an allotter switch has successively brought into service desired ones of said
50 automatic switches to operate another of said allotter switches, and means to advance the first of said allotter switches into position for reoperation when the last of said allotter switches has completed its operation.

5. In a telephone exchange system, two groups of automatic switches, an allotter switch individual to each of said groups, and automatic means to alternately operate said allotter switches to successively bring
60 into service desired ones of the automatic switches controlled by them.

4. In a telephone exchange system, two groups of automatic switches, an allotter switch individual to each of said groups,
65 means to operate one of said allotter

switches to successively bring into service desired ones of the automatic switches controlled by it, means operative after said allotter switch has successively brought into service desired ones of said automatic switches to operate the other of said allotter switches, and means operative upon the completion of operation of said second allotter switch for reoperating the first of said allotter switches.

5. In a telephone exchange system, two groups of automatic switches, an allotter switch individual to each of said groups, each of said allotter switches having a resting position, a plurality of allotting positions, and an awaiting position, means to operate one of said allotter switches to successively bring into service desired ones of the automatic switches controlled by it, means to advance said allotter switch to its resting positions, means operative upon the arrival of said allotter switch in its resting position to move the second of said allotter switches from its awaiting position into an allotting position, means operative upon the advancement of said second allotter switch to move said first allotter switch from its resting position into its awaiting position, means to operate said second allotter switch to successively bring into service desired ones of the automatic switches controlled by it, means to advance said second allotter switch to its resting position, means operative upon the arrival of such second allotter switch in its resting position to move said first allotter switch from its awaiting position into an allotting position, means operative thereupon to advance said second allotter switch from its resting position to its awaiting position, and means to reoperate said allotter switches.

6. In a telephone exchange system, a plurality of groups of automatic switches, an allotter switch individual to each of said groups, automatic means to successively operate said allotter switches to bring into service desired ones of the automatic switches controlled by them, means to remove a desired one of said allotter switches from service, and means operative upon such removal to allow successive reoperation of the others of said allotter switches.

7. In a telephone exchange system, two groups of automatic switches, an allotter switch individual to each of said groups, automatic means to alternately operate said allotter switches to successively bring into service desired ones of the automatic switches controlled by them, means to remove a desired one of said allotter switches from service, and means operative upon such removal to allow reoperation of the other of said allotter switches upon completion of a cycle of operation.

8. In a telephone exchange system, two

groups of automatic switches, an allotter switch individual to each of said groups, automatic means to alternately operate said allotter switches to successively bring into service desired ones of the automatic switches controlled by them, a device operable at will to render ineffective a desired one of said allotter switches, and means under the control of said device to allow reoperation of the other of said allotter switches upon the completion of a cycle of operation.

9. In a telephone exchange system, two groups of automatic switches, an allotter switch individual to each of said groups, automatic means to alternately operate said allotter switches to successively bring into service desired ones of the automatic switches controlled by them, a device operable at will to render ineffective a desired one of said allotter switches, means under the control of said device to allow reoperation of the other of said allotter switches upon the completion of a cycle of operation, means to release said device to allow said allotter switches to be again operated in succession, and a signal to indicate the proper time for the release of said device.

10. In a telephone exchange system, two groups of automatic switches, an allotter switch individual to each of said groups, means to alternately operate said allotter switches to successively bring into service desired ones of the automatic switches controlled by them, an alarm circuit, and means to complete said alarm circuit if both of said allotter switches are simultaneously brought into such positions respectively, that each allotter would normally bring into service one of said automatic switches.

11. In a telephone exchange system, two groups of automatic switches, an allotter switch individual to each of said groups, means to alternately operate said allotter switches to successively bring into service desired ones of the automatic switches controlled by them, and means to prevent any of said automatic switches from being brought into service should both of said allotter switches come to rest in such positions respectively, that each would normally bring into service a desired one of said automatic switches.

12. In a telephone exchange system, automatic switches, sending equipment including a counting device, means to actuate said counting device in response to movement of said automatic switches, an intermediate controlling device operable at desired times to control the operation of said counting device, means to actuate said counting device under the control of said intermediate controlling device at certain times, and means to actuate said counting device irre-

spective of said intermediate controlling device at other times.

13. In a telephone exchange system, automatic switches, an interrupting device associated with each of said automatic switches, sending equipment including a set of counting relays, means to operate an associated interrupting device upon movement of one of said automatic switches, means to successively actuate said counting relays under the control of said interrupting device, an intermediate controlling device operable at desired times to control the operation of said set of counting relays, means to actuate said counting relays under the control of said intermediate controlling device at certain times, and means to actuate said counting relays irrespective of said intermediate controlling device at other times.

14. In a telephone exchange system, automatic switches, an interrupting device associated with each of said automatic switches, sending equipment including a set of counting relays, means to operate an associated interrupting device upon movement of one of said automatic switches, means to successively actuate said counting relays under the control of said interrupting device, a relay operable at desired times in response to the operation of one of said interrupting devices to control the operation of said set of counting relays, means to actuate said counting relays under the control of said relay at certain times, and means to actuate said counting relays irrespective of said relay at other times.

15. In a telephone exchange system, automatic switches, sending equipment including a counting device, a variably adjustable controlling device, means to actuate said counting device in response to the movement of said automatic switches, means to operate said counting device under the control of said automatic switches, a relay operable at desired times in response to the movement of said automatic switches to control the operation of said counting device, means to actuate said counting device under the control of said relay when said controlling device is in certain positions, and means to actuate said counting device irrespective of said relay when said controlling device is in certain other positions.

16. In a telephone exchange system, automatic switches, an interrupting device associated with each of said automatic switches, sending equipment including a set of counting relays, a variably adjustable controlling device, means to operate an associated interrupting device upon movement of one of said automatic switches, means to successively actuate said counting relays under the control of said interrupting device, a relay

- operable at desired times in response to the operation of one of said interrupting devices to control the operation of said set of counting relays, means to actuate said counting 5 relays under the control of said relay when said controlling device is in certain positions, and means to actuate said counting device irrespective of said relay when said controlling device is in certain other positions.
17. In a telephone exchange system, calling and called lines, a train of automatic switches, means to operate said switches successively to establish connection between a 10 calling and a called subscriber's line, sending equipment including a counting device, means to actuate said counting device in response to movement of said automatic switches, a relay operable at desired times in 15 response to the movement of said automatic switches, means to actuate said counting device irrespective of said relay in response to movement of the first switch of said train of automatic switches, and means to actuate 20 said counting device under the control of said relay in response to movement of others of said automatic switches.
18. In a telephone exchange system, calling and called subscribers' lines, a train of 25 automatic switches for interconnecting a calling and called subscriber's line, an interrupting device associated with each of said automatic switches, sending equipment including a set of counting relays, means to 30 operate an associated one of said interrupting devices upon movement of one of said automatic switches, a variably adjustable controlling device, a relay operable at desired times in response to the operation of 35 one of said interrupting devices, means to actuate said counting relays under the control of the interrupter associated with the first switch of said train of switches, means to actuate said counting relays under the 40 control of said relay in response to movement of other switches of said train when said controlling device is in certain positions, and means to actuate said counting 45 relays irrespective of said relay in response to movement of said other automatic switches when said controlling device is in certain other positions.
19. In an automatic telephone exchange 50 system, calling and called subscribers' lines, an automatic switch including a movable brush shaft and a contact bank wherein multiple terminals are arranged in groups, outgoing lines terminating in said switch in said multiple terminal sets, an operator's 55 position, supervisory signals thereat to enable said subscribers to signal said operator, means to operate one of said automatic switches to advance its brush shaft over a selected group of terminal sets in search of 60

an idle outgoing line, and means operative 65 when all the lines of the selected group are busy to actuate a desired one of said supervisory signals.

20. In an automatic telephone exchange system, an automatic switch including a 70 movable brush shaft and a contact bank wherein multiple terminals are arranged in groups, outgoing lines terminating in said switch in said multiple terminal sets, an operator's position, a signal thereat, a polarized 75 relay to control the operation of said signal, means to operate one of said automatic switches to advance its brush shaft over a selected group of terminal sets in search of an idle outgoing line, and means operative 80 when all the lines of the selected group are busy to intermittently actuate said signal.

21. In an automatic telephone exchange system, an automatic switch including a 85 movable brush shaft and a contact bank wherein multiple terminals are arranged in groups, outgoing lines terminating in said switch in said multiple terminal sets, an operator's position, a visual signal thereat, 90 means to operate one of said automatic switches to advance its brush shaft over a selected group of terminal sets in search of an idle outgoing line, and means operative 95 when all the lines of the selected group are busy to actuate said signal and to supply an audible signal to said operator.

22. In an automatic telephone exchange system, calling and called subscribers' lines, an A operator's position, a signal thereat, a 100 polarized relay to control the operation of said signal, a B operator's position, means to extend a calling line from said A operator's position to said B operator's position, an automatic switch under the control of 105 said B operator to extend a desired connection, said automatic switch including a movable brush shaft and a contact bank wherein multiple terminals are arranged in groups, outgoing lines terminating in said switch in said multiple terminal sets, means to operate said automatic switch to advance its brush shaft over a selected group of terminal sets in search of an idle outgoing line, and means operative 110 when all the lines of the selected group are busy to intermittently actuate said signal.

23. In an automatic telephone exchange system, an automatic switch including a movable brush shaft and a contact bank 115 wherein multiple terminals are arranged in groups, outgoing lines terminating in said switch in said multiple terminal sets, a reversing switch, an operator's position, a signal thereat, means to operate one of said 120 automatic switches to advance its brush shaft over a selected group of terminal sets in search of an idle outgoing line, and means 125

- operative when all the lines of the selected group are busy to bring into service said reversing switch to intermittently actuate said signal.
- 5 24. In an automatic telephone exchange system, calling and called subscribers' lines, an A operator's position, a visual signal thereat, a polarized relay to control the operation of said signal, a B operator's position, means to extend a calling line from said A operator's position to said B operator's position, an automatic switch under the control of said B operator to extend a desired connection, said automatic switch including
- 10 15 a movable brush shaft and a contact bank wherein multiple terminals are arranged in groups, outgoing lines terminating at said switch in said multiple terminal sets, a reversing switch, means to operate said automatic switch to advance its brush shaft over the selected group of terminal sets in search of an idle outgoing line, and means operative when all the lines of the selected group are busy to bring into service said reversing
- 20 25 switch to intermittently actuate said signal and to supply an audible signal to said A operator.
25. In a multi-office telephone exchange system, calling and called lines, an operator's position, means for extending a calling line to said position, means for automatically indicating the number of a called line at said position, a sending device to control the operation of said number indicating means, and means to delay operation of said sending device until said operator is in readiness to receive a call.
- 30 35 40 45 50 55 60 65 70 75 80 85 90 95 100 105 110 115 120 125
26. In a multi-office telephone exchange system, calling and called lines, an operator's position, means for extending a calling line to said position, a signal at said position, means to operate said signal to inform said operator that a calling line has been extended to said position, means for automatically indicating the number of a called line at said position, a sending device to control the operation of said number indicating means, and means to prevent the actuation of said signal until said operator is in readiness to receive a call.
27. In a multi-office telephone exchange system, calling and called lines, an operator's position, means for extending a calling line to said position, operator's equipment at said position whereby a connection may be further extended, a signal at said position, means to operate said signal to inform said operator that a calling line has been extended thereto, means for automatically indicating the number of a called line at said position, a sending device to control the operation of said number indicating means, and means to prevent the actuation of said signal and to delay operation of said

sending device until said operator is in readiness to receive a call.

28. In a multi-office telephone exchange system, calling and called lines, an operator's position, means for extending a calling line to said position, means at said operator's position for automatically indicating the number of a called line, operator's equipment at said position to be used in further extending a desired connection from said position, a sending device to control the operation of said number indicating means, and means to delay operation of said sending device until said operator's equipment is in its normal position.

29. In a multi-office telephone exchange system, calling and called lines, an operator's position, a trunk line, means including said trunk line for extending a calling line to said position, a connecting plug associated with said trunk line, a plurality of jacks to be used in extending the desired connection, means for automatically indicating the number of a called line at said position, a sending device to control the operation of said number indicating means, and means to prevent operation of said sending device when said plug has not been removed from the one of said jacks last used.

30. In a multi-office telephone exchange system, calling and called lines, an A operator's position, a sending device thereat, a marginal relay to control the operation of said sending device, a B operator's position, a number indicating device thereat, means to extend a calling line to said A operator's position and thence to said B operator's position, means to operate said number indicating device under the control of said sending device, and means to prevent the energization of said relay until said B operator is in readiness to receive a call.

31. In a multi-office telephone exchange system, calling and called subscribers' lines, an A operator's position, a sending device thereat, a relay to control the starting of said sending device, a trunk line, a B operator's position, means including said trunk line to extend a calling line to said B operator's position, connecting means associated with said trunk line to further extend a desired connection from said B operator's position, a number indicating device at said B operator's position, means to operate said number indicating device under the control of said sending device, and means to prevent the energization of said relay when said B operator has not released said connecting means after a previous connection.

32. A multi-office telephone exchange system, calling and called subscribers' lines, an A operator's position, a sending device thereat, a relay to control the starting of said sending device, a trunk line, a B oper-

- ator's position, a signal thereat, a number indicating device at said B operator's position, a trunk line, means including said trunk line to extend a calling line to said 5 B operator's position, connecting means associated with said trunk line to further extend a desired connection from said B operator's position, means to operate said signal to inform said B operator that a calling line has been extended to said B operator's position, a second relay arranged to control the operation of said signal, said second relay being under the control of said sending device, means to operate said number indicating device under the control of said sending device, means to prevent the energization of said first relay when said B operator has not released said connecting means after a previous connection and 10 20 means operative as a result of the deenergized condition, of said first relay to prevent the display of said signal.
33. In an automatic telephone exchange system, a selector switch, a trunk line leading to said selector switch, means to control the busy or idle condition of said trunk line, means to release said selector switch, and means to prevent the release of said selector switch until the busy condition has 25 30 been removed from said trunk line for a predetermined length of time.
34. In an automatic telephone exchange system, a selector switch, a sending device to control the selective operations of said switch, a relay, an interrupter, a time measuring device including said interrupter, and means to release said selector switch only after said relay has been deenergized for a period of time determined by said timing 35 40 device.
35. In an automatic telephone exchange system, first and second selector switches, sending devices to control the selective operations of said switches, means to release one of said second selector switches only after a predetermined time interval has elapsed since its release by an associated one of said first selectors, and means to prevent operation of a sending device associated 45 50 with another first selector switch which may seize the aforesaid second selector, until said second selector switch is in readiness for reoperation.
36. In an automatic telephone exchange system, a selector switch, a sending device to control the selective operations of said switch, a relay, means to release said selector switch only after said relay has been deenergized for a predetermined length of 55 60 time, and means to delay operation of said sending device until said selector switch is in readiness for operation.
37. In an automatic telephone exchange system, calling and called subscribers' lines, a plurality of first selector switches, a plurality of sending devices associable therewith, a plurality of second selectors, means to operate a desired one of said first selectors and a desired one of said second selectors to extend the connection from a calling line 65 70 toward a called line, a relay associated with each of said second selectors, means to release a positioned second selector only after said relay has been deenergized for a predetermined length of time, means to control 75 the busy condition of said second selectors at said first selectors, and means to delay operation of said sending device until said selector switch is in readiness for reoperation. 80
38. In an automatic telephone exchange system, a first selector switch, a second selector switch, a sending device, means to position said switches under the control of said sending device, a relay, means to release said second selector only after said relay has been deenergized for a predetermined length of time, other first selector switches, a trunk leading to said second selector switch, means whereby another one 90 95 of said first selector switches may seize said trunk line while said second selector switch is awaiting restoration, a sending device associated with said other first selector, and means to prevent operation of said last mentioned sending device until said second selector is in readiness for reoperation. 100
39. In a telephone exchange system, calling and called subscribers' lines, means to establish a connection between a calling and a called subscriber, a condenser in each side of the talking circuit, means to reverse the direction of current flow in the calling portion of said talking circuit, a relay under the control of the called subscriber to control said current reversals, said relay being normally bridged across said condensers, and means to prevent the discharge of said condensers from affecting the condition of said relay. 105 110
40. In a telephone exchange system, calling and called subscribers' lines, means to establish connection between a calling and a called subscriber, a condenser in each side of the talking circuit, means to reverse the direction of current flow in the calling portion of said talking circuit, a relay under the control of the called subscriber to control said current reversals, said relay being normally bridged across said condensers, a 115 second relay, and means controlled by said second relay to prevent the discharge of said condensers from affecting the condition of said first mentioned relay and to absorb said condenser discharge during said current reversals. 120 125
41. In a telephone exchange system, calling and called subscribers' lines, a plurality

- of offices, means to establish a connection between a calling and a called subscriber through said offices in tandem, an A operator's position, a supervisory signal thereat, 5 a polarized relay to control said signal, a condenser in each side of the talking circuit, means to reverse the direction of current flow through said polarized relay to control the operation of said signal, a relay under the control of the called subscriber to control said current reversals, said relay being normally bridged across said condensers, and means to prevent the discharge of said condensers from affecting the condition of said relay. 15

In witness whereof, we hereunto subscribe our names this 27th day of October, A. D. 1917.

ALBEN E. LUNDELL.
EDGAR H. CLARK.
